UNITED STATES PATENT OFFICE.

FREDERICK J. SCUDDER, OF LONG ISLAND, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed March 31, 1921. Serial No. 457,253.

To all whom it may concern:

Be it known that I, FREDERICK J. SCUDDER, a citizen of the United States of America, residing at Long Island, in the county of 5 Queens and State of New York, have invented certain new and useful Improvements in Telephone-Exchange Systems, of which the following is a full, clear, concise, and exact description.

10 This invention relates to a telephone system and more particularly to a system in which connections are established between subscribers' lines by means of mechanical switching devices.

15 In large telephone exchanges comprising several offices, some of which may be closely associated and others of which may be quite widely separated, it is desirable to employ inter-office trunk lines for connecting the 20 different offices of the exchange and for extending connections to toll trunks leading to exchanges in distant communities, that are designed to provide the most efficient talking conditions. This result is attained 25 by providing the trunk lines which extend to distant offices or to distant exchanges with loading coils and by omitting such loading coils from inter-office trunks which connect adjacent offices.

30 Heretofore it has been the practice in large exchanges in which connections are extended by mechanical switching devices, to provide selector switches in the originating offices which are under the control of a 35 common office sending mechanism for extending connections to trunks leading to other offices, or to other switches local to the originating office. These switches are positioned in accordance with the office designations of the lines with which the connections 40 are desired. The talking circuits extending to the brushes of the switches are provided with repeating coils for increasing the efficiency of speech transmission, talking current being supplied to the line of the calling 45 subscribers through the primary windings of these coils.

To attain the most efficient transmission of speech through the windings of the repeating coils and over the different classes of inter-office trunks with which connections 50 may be established, it is desirable to provide for different ratios of transformation through the windings of the repeating coils, that is, a greater ratio of transformation if

the outgoing office trunk is of considerable length and loaded, than if the trunk is of short length and without loading. It is also desirable to completely by-pass the repeating coils by direct metallic connections when 60 connections are extended to an operator's position. It is therefore an object of this invention to provide means under the control of an auxiliary switch associated with a link circuit for altering the connections of the windings of the repeating coil associated with the link circuit in accordance with the character of the trunk circuit to which a connection is extended from the link 65 circuit.

Now particularly it is an object of the invention to provide means for altering the number of effective turns in the secondary winding of the repeating coil associated with a selector link for producing a desired 70 ratio of turns between the primary and secondary windings of the repeating coil through the selective positioning of the sequence switch associated with the selector 75 link.

In connection with this invention the office sender is provided with a plurality of code registers which are set in accordance with the office designation of a desired line, and with a plurality of locking register relays 80 which are selectively operated in accordance with the setting of the code registers. Certain of these relays control the circuits of the sender in accordance with the class of the call which is to be established, some of the 85 relays through the usual group of counting relays control the setting of the district and office selector switches to extend the call to the office in which the desired line terminates, and other of the relays through co-operation of the counting relays control the 90 selective movements of the district sequence switch for the purpose of altering the connections of the repeating coil.

The invention may be more readily understood by reference to the following description considered in connection with the accompanying drawings in which Fig. 1 shows one of a group of lines terminating in a full mechanical office of the exchange and a rotary line switch individual to such line by means of which the subscriber's line may be connected to an idle district selector switch; Fig. 2 shows a district selector and a sender finder switch, together with the cir- 100

105

110

cuits and controlling mechanism associated therewith; Fig. 3 shows an office selector switch together with the circuits and controlling mechanism associated therewith; 5 Fig. 4 shows an incoming selector switch provided with mechanism for applying ringing current to the terminals of a called line, together with the circuits and mechanism for controlling such switch; Fig. 5 shows the 10 mechanism and circuits of a final selector switch and the line of a subscriber to which the selector switch has access; Fig. 6 shows a time measure switch and translator control sequence switch associated with the central 15 office sending mechanism; Fig. 7 shows a portion of the circuit of a sending mechanism comprising a stepping relay, a group of counting relays, a sequence switch for controlling the circuits of the sender, and a 20 class sequence switch for altering the circuits of the sender in accordance with the class of the call which is to be extended; Fig. 8 shows the code registers which are set in accordance with the first three code 25 or office designation digits dialed by the calling subscriber, and the steering switch which successively associates the code registers and the number registers shown in Fig. 9 with the impulse circuit extending to the calling 30 subscriber's line; Fig. 9 shows number registers which are set by the calling subscriber in accordance with the numerical designation of the desired line; Fig. 10 shows groups of translator register relays which are selectively 35 operated by the translator switch and pulse machine shown in Fig. 11 in accordance with the setting of the code registers for determining the setting of the class switch shown in Fig. 7, the setting of the 40 district selector shown in Fig. 2 and for setting the sequence switch of the district selector to determine the connection of the repeating coil into the talking circuit. Fig. 11 shows a translator switch and a development 45 of the pulse machine drum for setting the register relays; and Fig. 12 is a diagram showing the manner in which the several sheets of the drawing should be arranged to show as much of a complete organization 50 of circuits as is necessary to illustrate the manner in which the connections may be established between subscribers' lines.

The calling subscriber's line K is of the usual type provided with a transmitter, receiver and a call bell and since it terminates in a full mechanical exchange is also equipped with an impulse sending dial S of the usual type.

The subscriber's line terminates in an individual trunk finding switch of the well known rotary step by step type, which through a plurality of wipers, has access to a group of trunk lines terminating in district selector switches. The switch is provided with a stepping magnet for advancing the wipers

over terminals of the trunk lines in search of an idle trunk and for advancing the wipers around to normal position upon the release of the established connections.

The district selector, office selector, incoming selector and final selector diagrammatically disclosed in Figs. 2 to 5 inclusive are of the type shown and described in the patent to E. B. Craft and J. N. Reynolds No. 1,123,696 issued January 5, 1915. Each of the switches has a vertically disposed switch shaft provided with five sets of brushes, each brush set having access to a bank of 100 terminals. For driving the switch shaft upwardly an up-drive magnet is provided which when energized presses the switch shaft against a constantly driven power drum, and for restoring the switch shaft to normal position a second down-drive magnet is provided which when energized presses the switch shaft against a second constantly driven power drum. For determining the particular set of brushes on the switch shaft to be employed a tripping spindle is provided as described in the patent hereinbefore referred to. The final selector switch differs from the other selector switches in being provided with additional means comprising a second up-drive magnet and driving drum for driving the switch shaft upwardly at two different speeds, rapidly during brush selection and group selection, and more slowly during the terminal selection movement of the switch shaft.

The translator switch TS shown in Fig. 11 is of the same type as the switch shown in the aforesaid patent, but is equipped with 10 sets of brushes arranged in 5 pairs, the brush sets comprising each pair being arranged to be tripped together.

The sender finder switch SF shown in Fig. 2, the time measure switch TM shown in Fig. 6, the register steering switch RS shown in Fig. 8 and the registers A, B, C, TH, H, T and U shown in Figs. 8 and 9 are of the well-known step by step type, the wipers of which are advanced by stepping magnets. With the exception of sender finder switch SF, the wipers of these registers are restored to normal position by being advanced by their respective stepping magnets around to normal. Finder switch SF has no normal position, the wipers thereof resting in contact with the bank terminals last employed when the switch is idle.

The pulse machine PM shown in Fig. 11 comprises a drum of insulating material in which a plurality of circumferential rows of contact segments are embedded, these segments being connected to a source of current through a common slip ring. A plurality of brushes engage the several rows of segments and are arranged to be variously connected to the contacts in the 10 banks of translator switch TS through suitable distributing

blocks (not shown) for conducting impulses of current from the several segments to the bank terminals of the translator switch.

For controlling the circuits associated with the several selector switches and the circuits of the office sender, auxiliary switches are provided. These switches may be of the type described in the patent to Reynolds et al No. 1,127,808, issued February 9, 1915 and known in the art as sequence switches. Each sequence switch comprises a rotatable shaft driven from a constantly operated source of power through a magnetic clutch member and carries a plurality of circuit closing cams which at different radial positions of the shaft cause the closure of a plurality of contacts. The cam contacts associated with each sequence switch are closed only in the positions indicated by the numerals associated with each contact with the exception of the master contacts 201, 301, 401, 501, 601, 701 and 751 associated respectively with sequence switches 200, 300, 400, 500, 600, 700 and 750, these latter contacts being open in the positions indicated by the numerals appearing adjacent such contacts and closed in all other positions.

The different pieces of apparatus employed in the system having now been briefly described it is thought that a clearer understanding of the invention may be had from a description of the method of establishing a call from the station of the calling subscriber K in an originating office X to the station of a called subscriber L whose line terminates in a terminating office Y. The apparatus shown in Figs. 4 and 5 is located in office Y, whereas the remaining apparatus is located in the originating office X. It will first be assumed that the Offices X and Y are situated adjacent to each other and that therefore the interoffice trunk is short and without loading and that the designation of the desired line is LISpenard 9532.

45 *Initiation of full mechanical call.*

The calling subscriber upon initiating a call closes a circuit for the line relay 101 of the trunk hunting switch 100, which circuit may be traced from grounded battery through the right hand winding of relay 101, the innermost lower armature and back contact of cutoff relay 102, over line conductor 103, through the substation of subscriber's line K, and thence back over line conductor 104 to ground at the upper armature and back contact of cutoff relay 102. The line relay energizes in this circuit and closes a circuit for the stepping magnet 105 of the switch 100, which circuit may be traced from grounded battery through the winding and armature contacts of magnet 105, conductor 106, the lowermost armature and back contact of relay 102, the right hand armature and front contact of relay 101, conductor 107

and thence to ground through the wiper 108 and the normal contact of the bank to which this wiper has access. The magnet 105 upon energizing in this circuit advances the wipers 108, 109, 110, 111, 112 and 113 of switch 100 to the second contacts of the respective banks to which they have access. As the second contact which wiper 108 engages is permanently connected to ground, the magnet 105 continues to step the wipers to the third set of contacts leading to the first of the group of trunks to which the switch 100 has access.

If the first trunk of the group is busy, there will be a ground potential on the test terminal thereof appearing in the lowermost bank of the switch and the switch will therefore continue stepping until an idle trunk is found, upon the test terminal of which battery potential appears. When this battery potential is encountered a circuit is closed from battery through the right hand contacts of sequence switch cam 202 of the district selector to which the first idle trunk extends, through the inner left hand armature and back contact of sleeve relay 226, over test conductor 114 wiper 108, conductor 107, the left hand armature and front contact and left hand winding of relay 101, conductor 115 and thence to ground through both windings of cutoff relay 102. The energization of the cutoff relay 102 opens the circuit of the stepping magnet 105 at its lowermost armature and back contact and at its upper armature and back contact, and at its upper armature and front contact and uppermost lower armature and front contact, this relay extends the conductors 103 and 104 of the subscriber's line to the wipers 111 and 113 of the switch 100 and thence to the trunk conductors 116 and 117 leading to the selected district selector. Relay 102 also at its intermediate lower armature and front contact closes a circuit extending through the right hand winding of sleeve relay 226 of the district selector switch, through the break contacts of the left hand armature of slow releasing relay 227, the lower right hand contact of sequence switch cam 203 (1 to 2½) sleeve conductor 118, wiper 109, winding of the marginal message register magnet 119, conductor 120, the intermediate lower armature and front contact of cutoff relay 102 and thence to ground through the upper winding of the cutoff relay. The sleeve relay 226 of the district selector switch energizes in this circuit, but owing to its marginal nature the message register magnet 119 does not energize at this time.

For making the calling subscriber's line K busy to all calls incoming thereto, battery potential is connected to the multiple test terminals 121 of the calling line appearing in the banks of all final selectors having access to this line, over conductor 122,

- through wiper 110, segment 123 and grounded battery. Wiper 112 through the grounded segment 124 prepares a circuit extending over conductor 125 to the back contact of the right hand armature of line relay 101 preparatory to restoring the finder switch to normal when the cutoff relay 102 becomes de-energized upon the termination of the connection.
- 10 Upon the energization of sleeve relay 226 a circuit is established for the line relay 228 of the district selector switch 250 which circuit extends from grounded battery through the right hand winding of this relay, the lower right hand contact of sequence switch cam 204, conductor 229, the lower contacts of sequence switch cam 205, conductor 230 and thence to ground through the front contact and right hand armature of sleeve relay 226. At its inner left hand armature and front contact relay 226 connects ground potential to the test conductor 114 of the selected trunk to mark the trunk busy to other line switches, and at the back contact of this armature disconnects the source of battery potential which up to the time the selector switch was seized marked the selector switch as idle. Line relay 101 now deenergizes.
- 15 Relay 228, upon energizing, closes a circuit for driving the sequence switch 200 of the district selector switch out of its normal position 1 and into position 2; this circuit extending from grounded battery through the magnet winding 200, conductor 231, the upper left hand contact of sequence switch cam 206, the inner right hand armature and front contact of relay 228 and thence to ground at the lower right hand contact of sequence switch cam 207. The sequence switch magnet energizes in this circuit and under the control of the master cam 201 drives the sequence switch into position 2 in which position a circuit is closed from grounded battery through the winding of relay 227, the upper left hand contact of sequence switch cam 208 and thence to ground. Relay 227 upon energizing closes a holding circuit for the sleeve relay 226 extending through the right hand winding of relay 226, the make contacts of the left-hand armature of relay 227 and thence to the sleeve conductor 118 over the upper right hand contact of sequence switch cam 203 (13 to 16) this circuit being maintained through position 16 of the sequence switch or until relay 227 becomes de-energized.
- 20 Upon reaching position 2 the sequence switch connects a new holding ground to the test conductor 114 extending over conductor 232 and through the upper right hand contact of sequence switch cam 208, which holding ground is maintained through position 18₁ of the sequence switch.
- 25 As soon as the sequence switch reaches position 1₂ a circuit is closed for the stepping magnet 233 of the sender finder SF extending from grounded battery through the interrupter contacts and winding of magnet 233, the upper left hand contact of sequence switch cam 209 (1₂ to 2) conductor 234 and thence to ground through the inner right hand armature and front contact of relay 228 and the lower right hand contact of sequence switch cam 207. A circuit is also closed at this time through the winding of stepping magnet 233, the winding of cut-in relay 235 and thence to ground at the lower left hand contact of sequence switch cam 208. Relay 235 does not energize at this time, however, since its winding is shunted by ground connected to the armature of line relay 228.
- 30 As soon as sequence switch 200 leaves position 1 the initial energizing circuit of line relay 228 is opened at the lower right hand contact of sequence switch cam 204, but this relay remains locked over a circuit extending from grounded battery through its left hand winding, its left hand armature and front contact, the upper left hand contact of sequence switch cam 210, conductor 236, the lower right hand contact of sequence switch cam 211, conductor 237, test wiper 238 of the sender finder switch SF and to ground at busy contacts of the bank over which this wiper moves. As soon, however, as an idle sender is found, the wiper 238 will find no ground on the terminal corresponding to such idle sender and the line relay 228 will thereupon de-energize, opening at its inner right hand armature and front contact, the circuit extending through the stepping magnet 233, and closing at its inner right hand armature and back contact a circuit for driving sequence switch 200 out of position 2 and into position 3. This circuit may be traced from grounded battery through the sequence switch magnet 200, conductor 231, the upper right hand contact of sequence switch cam 206, the inner right hand armature and back contact of relay 228 and thence to ground at the lower right hand contact of sequence switch cam 207.
- 35 As soon as line relay 228 de-energizes the shunt around the winding of relay 235 is removed at the inner right hand armature and front contact of relay 228 and relay 235 thereupon energizes in series with stepping magnet 233, the current flowing through this circuit, however, not being sufficient to cause the energization of the stepping magnet. Relay 235, upon energizing, closes a circuit extending from ground through the inner left hand armature and front contacts of this relay over wiper 238 and the terminal upon which it is resting, conductor 624 and thence to grounded battery through the left hand

winding of differential relay 625. Relay 625 energizes in this circuit and closes a circuit for advancing the time measure switch TM, extending from grounded battery 5 through the winding of stepping magnet 626, over wiper 627 and the normal contact of the bank with which it is associated, through the interrupter 628, the outermost left-hand armature and back contact of relay 629 and thence to ground at the armature and front contact of relay 625. Under the influence of the interrupter 628, the stepping magnet 626 advances the wipers of the time measure switch TM from their 10 normal resting positions to the second position contacts in the several banks of contacts to which they have access respectively. With the wiper 630 in engagement with the second contact 631 of the bank with which it is associated, a circuit is closed for relay 629 which may be traced from grounded battery through the winding of this relay, over conductor 632, contact 631 and thence to ground through wiper 630. 15 Relay 629, upon energizing in this circuit, opens at its outer left hand armature and back contact the initial stepping circuit of the time measure switch TM and closes a new stepping circuit for advancing the time 20 measure switch from position 2 into position 6, this circuit extending from grounded battery through the winding of stepping magnet 626, the armature contacts of stepping magnet 626, wiper 633, the Nos. 2 to 5 contacts of the bank with which this wiper is associated, which contacts are tied together, conductor 634, the outer left hand armature and front contact of relay 629 and thence to ground at the armature and front contact 25 of relay 625. This movement of switch TM measures off a definite time interval before the dial tone is given to the calling subscriber. Relay 629 also closed a circuit extending from grounded battery through the 30 winding of stepping relay 800, conductor 801, the innermost left hand armature and front contact of relay 629, conductor 635, wiper 239 of the sender finder SF, conductor 240, the upper left hand contact of sequence 35 switch cam 212 (2 to 10 $\frac{1}{2}$), trunk conductor 117, wiper 113 of the trunk finding switch 100, upper armature and front contact of relay 102, line conductor 104, through the calling subscriber's sending dial S, line conductor 103, the innermost lower armature and front contact of relay 102, wiper 111, conductor 116, the lower left hand contact of sequence switch cam 213 (2 to 10 $\frac{1}{2}$), conductor 241, the outer left hand armature and 40 front contact of relay 235, wiper 242 of the sender finder SF, conductor 636, the right hand armature and front contact of relay 629 and thence to ground through the right hand winding of balancing resistance 45 coil 637. The stepping relay 800 energizes in this circuit and at its left hand armature and front contact closes a circuit for the slow releasing relay 802, this circuit extending from grounded battery through the winding of relay 802 and thence to ground 70 through the left hand armature and front contact of relay 800. A circuit is now closed for sending a dialing tone to the calling subscriber which circuit may be traced from ground through the right hand make contacts of slow releasing relay 802, conductor 803, wiper 804 of the steering switch RS, the normal contact 805 of the bank with which this wiper is associated, conductor 806, through the left hand winding of balancing coil 637 and thence to ground through the secondary winding of the tone coil 638. The tone current flowing in this circuit is inductively transmitted to the substation of the calling subscriber through the right 75 hand winding of balancing coil 637, over the circuit previously traced. 80 At the time the sender finder SF seized the idle office sender and the time measure switch TM advanced out of its normal position, a ground potential was connected to test conductor 624 to mark the office sender busy to all other sender finders, over a circuit extending from ground through the wiper 630 of the time measure switch, the 85 contacts of the bank with which this wiper is associated, conductor 640, conductor 641, the right hand winding of differential relay 625 and thence to the test conductor 624. The right hand winding of relay 625 being short 90 circuited, this relay is still maintained energized over its left winding. 95 The calling subscriber receiving the dialing tone over the circuit previously traced, 100 proceeds to dial the number of the desired line. Under the assumption that the subscriber desires a connection with a subscriber's line L in an adjacent office, which subscriber's line is listed in the directory as LISpenard 9532 and that this office is 105 reached through a district selector switch 250 and office selector switch 350 local to the calling subscriber's office, and through an incoming selector 450 and a final selector 550 at the office in which the desired line 110 terminates, the subscriber proceeds to dial three letters corresponding to the office designation of the office in which the desired line is located and then dials four digits representing the number of the line in such office. 115 In the case assumed, the calling subscriber will dial the letters L I S and will then dial the numerals 9 5 3 2. The three letters, which represent the office code, will not only cause the setting of the district selector and office selector switches to choose the desired office, but will also cause the selection of a proper talking path for efficient speech 120 transmission between the offices, and the setting of the class sequence switch 750 for de- 125 130

termining the adjustment of the circuits of the office sender in accordance with the class of the call which is being extended.

5 *Setting the code and numerical registers.*

In response to the first impulse dialed by the calling subscriber in accordance with the first letter of the office designation the stepping relay 800 de-energizes and closes a 10 circuit for the stepping magnet 807 of the first code register A, which stepping circuit may be traced from grounded battery through the left hand armature and back contact of preliminary pulse relay 808, conductor 809, the winding of slow release relay 810, conductor 811, the winding of stepping magnet 807, the back contact and outer right hand armature of relay 808, the normal bank contact 812 of the register steering switch RS, wiper 813 normally in engagement therewith, conductor 814, the left hand armature and front contact of slow releasing relay 802 and thence to ground through the armature and back contact of stepping relay 800. In response to this impulse the stepping magnet 807 advances the wipers of the register A one step as soon as the circuit of the stepping magnet 807 is again opened. Upon the reenergization of stepping relay 800 and in response to successive impulses of the first code letter L, the register A advances its wipers into contact with the fifth set of contacts of its banks. To insure that the stepping magnet 807 shall remain energized long enough upon each de-energization of stepping relay 800 to cause a complete step of the register, a circuit is closed 30 through relay 841 in parallel with the winding of stepping magnet 807, which circuit may be traced from grounded battery through the inner right hand armature and back contact of relay 808, winding of relay 841, wiper 842, the normal contact of the bank with which it is associated, the armature and back contact of stepping magnet 807, and thence to ground at the armature and back contact of relay 800 over the circuit previously traced. Relay 841 energizes 40 in this circuit and closes a locking circuit for itself independent of the armature contacts of relay 800, which locking circuit extends over the circuit previously traced through the winding of relay 841, through the armature and back contact of relay 807, the outer right hand armature and back contact of relay 808, contact 812, wiper 813, thence to ground through the left hand armature and front contact of relay 841. Relay 841 is thus maintained energized until 50 stepping magnet 807 has moved its armature to the full extent of its movement, when the circuit through relay 841 is opened at the armature contacts of relay 807. Relay 841 at its right hand armature and front contact closes a holding circuit for slow relay 802

for holding this relay energized independent of the energization of relay 800.

The slow releasing relay 810 which was also energized in the circuit of stepping magnet 807 of the register A, maintains its 70 energization because of its slow releasing characteristic until the series of impulses transmitted through the magnet 807 ceases, when this relay de-energizes. Upon its initial energization, this relay closes a circuit 75 extending from grounded battery through the make contacts of its left hand armature and the winding of slow releasing relay 815, and this latter relay through its armature and front contact connects ground potential 80 to the conductor 640 for insuring that the office sender be maintained busy to all 85 sender finders during the setting of the register A. At its right hand armature and front contact, relay 810 also closes a circuit 85 extending from grounded battery through the winding of slow releasing relay 816, through the winding of stepping magnet 817 of the register steering switch RS, over conductor 818 through the right hand armature 90 and front contact of relay 810 and thence to ground over conductor 803, and the make contacts of the right hand armature of slow 95 releasing relay 802. As soon as relay 810 de-energizes, upon the cessation of impulses 100 flowing through the circuit of stepping magnet 807, the circuit previously traced through relay 816 and stepping magnet 817 is opened, causing the de-energization of 105 stepping magnet 817 which thereupon advances the wipers of the register steering switch RS from engagement with the normal contacts of the respective banks to which they have access into engagement with 110 the first contacts of the banks. The movement of wiper 813 now transfers the control circuit extending from the armature of stepping relay 800 over conductor 814, from the winding of stepping magnet 807 of register A, to the winding of stepping magnet 819 of the register B. Slow releasing relay 816 which was energized in series with the stepping magnet 817 during its energization maintains a ground potential connected to 115 the conductor 640 for holding the sender busy to all sender finders SF over a circuit extending from its armature and front contact to conductor 640. With the register steering switch RS in 120 position 1 the second series of impulses corresponding to the second code letter of the office designation causes the setting of the code register B in a manner similar to the setting of register A, the stepping circuit of the stepping magnet 819 of register B extending from grounded battery through the left hand armature and back contact of 125 relay 808, conductor 809, the winding of slow releasing relay 810, conductor 811, the winding of stepping magnet 819, conductor 130

820, bank contact 821, wiper 813 in engagement therewith, the left hand armature and front contact of relay 802 and thence to ground at the armature and back contact of relay 800. Under the assumption that the second code letter is I, the wipers of the code register B takes a setting on the No. 4 contacts of the banks with which the respective wipers make contact. Upon the termination of the impulses of the second code letter, the slow releasing relay 810 de-energizes in the manner previously described, causing the movement of the register steering switch RS from position 1 into position 2, in which position the control circuit previously traced through the stepping magnet 819 of the code register B is opened and the control circuit extended through the stepping magnet 822 of the code register C. With the wipers of the register steering switch RS in engagement with the second position contacts of the respective banks with which they are associated, a circuit is established for the relay 642 which may be traced from grounded battery through the right hand winding of this relay, conductor 643, contact 823, wiper 804 in engagement therewith, conductor 803 and thence to ground at the make contacts of the right hand armature of relay 802. Relay 642 upon energizing, closes a locking circuit for itself extending from grounded battery through its left hand winding and left hand armature and front contact to ground on conductor 640, and at its left hand armature and front contact closes a circuit for the control relay 644 of the translator control sequence switch 600. This circuit extends from grounded battery through the left hand winding of relay 644, the contact of sequence switch cam 602 (1 and 2), the armature and front contact of relay 642 and thence to ground on conductor 640.

45 *Setting the translator switch.*

Relay 644 energizes in this circuit and at its armature and front contact closes a circuit for driving the translator control sequence switch 600 out of position 1 and into position 2, this circuit extending from grounded battery through the magnet winding of sequence switch 600, the left hand contact of sequence switch cam 603, (1) and thence to ground through the armature and front contact of relay 644. In its movement from position 1 to position 2 the sequence switch is under the control of master contact 601 which insures that the sequence switch will move completely into position 2. In position 2 of sequence switch 600 a circuit is closed from battery through the right hand winding of relay 663, and the right hand armature and back contact of relay 656 to ground at cam 614. Relay 663 upon energizing closes an obvious circuit for re-

lay 650 which also energizes. Upon reaching position 2 sequence switch 600 closes a circuit for the up drive magnet 1100 of the translator switch TS, which circuit extends from grounded battery through the winding of magnet 1100, conductor 1101, the contact of sequence switch cam 604 (2) and thence to ground at the armature and front contact of relay 644. In response to its energization magnet 1100 presses the depending portion of the switch shaft 1102 of the translator switch TS against the constantly rotating up drive roller 1103 thereby causing the switch shaft 1102 and the brush sets carried thereby to be moved upwardly. This upward movement continues until the test brush 1104 encounters a terminal in the test bank 1105 which has been grounded through the bank contacts of code registers A and B. As soon as brush 1104 engages such a terminal a circuit is closed through the right hand winding of the differentially wound control relay 644 which may be traced from grounded battery through the right hand winding of this relay, the left hand contacts of sequence switch cam 605, conductor 1106, testing brush 1104, terminal 1107, conductor 1108, contact 824 and wiper 825 of the register A, conductor 826, contact 827 and wiper 828 of the code register B, conductor 829 and thence to ground at the lower left hand contact of sequence switch cam 606 (1 to 3). Current flowing through the right hand winding of relay 644 differentially balances the relay which thereupon de-energizes, opening at its armature and front contact the circuit previously traced through the up drive magnet 1100 of the translator switch thereby arresting the upward movement of the switch. The brush shaft of this switch is now positioned with a certain pair of the brush sets carried thereby in co-operative relation with a tripping finger on the tripping spindle 1109. Relay 644, upon de-energizing, also closes a circuit for driving the translator control sequence switch 600 out of position 2 and into position 3, this circuit extending from grounded battery through the magnet winding 600, the upper left hand contact of sequence switch cam 607 (2) and thence to ground at the armature and back contact of relay 644.

Upon leaving position 2, the initial energizing circuit extending through the left hand winding of relay 644 was opened at the contact of sequence switch cam 602, but this circuit is again established as soon as the sequence switch reaches position 3 and the relay 644 therefore again energizes. Upon reaching position 3 a circuit is established for the tripping magnet 1110 of the translator switch TS, extending from grounded battery through the winding of the tripping magnet, conductor 1111 and

thence to ground through the upper right hand contact of sequence switch cam 608 (3 to 5). The tripping magnet upon energizing in this circuit, rotates the tripping spindle 1109 to position tripping fingers to trip the pair of brush sets of the switch TS which have been positioned in operative relation to a pair of tripping fingers on the tripping spindle upon a subsequent movement of the switch shaft. It will be assumed that brush sets 1112 and 1113 shown in Fig. 11 of the drawing are the brush sets which are to be tripped at this time.

Control relay 644, upon re-energizing in position 3 of sequence switch 600, again closes a circuit for driving sequence switch 600 out of position 3 and into position 4. This circuit extending from grounded battery, through the winding of magnet 600, the left hand contact of sequence switch cam 603 (3) and thence to ground through the armature and front contact of relay 644. When sequence switch 600 reaches position 4 a circuit is again closed for the up drive magnet 1100 of the translator switch TS as previously traced, through the armature and front contact of relay 644. When the up drive magnet is thus energized, the switch shaft 1102 is driven upwardly and during the first part of its movement since at this time the tripping spindle 1109 is rotated, the selected pair of brushes 1112 and 1113 are tripped and during the subsequent upward movement of the switch shaft the brushes of these brush sets are caused to wipe over the terminals of the banks to which they have access until the test brush 1104 engages a terminal in the test bank 1105 corresponding to the group setting of the code registers. This terminal has ground potential connected thereto, through the wipers of the code registers. A circuit is now established, extending from grounded battery through the right hand winding of control relay 644, the left hand contacts of sequence switch cam 605, conductor 1106, test brush 1104, bank terminal 1114, conductor 1115, contact 830 and wiper 831 of the code register B, conductor 832, contact 833 and wiper 834 of the code register A, conductor 835 and thence to ground at the lower left hand contact of sequence switch cam 608 (1 to 5). Upon the closure of this circuit through the right hand winding of relay 644, the relay is differentially balanced and de-energizes, opening at its armature and front contact the circuit extending through up drive magnet 1110 of the switch TS to arrest the upward movement of the switch shaft and to position the selected sets of brushes beneath the groups of bank terminals corresponding to the setting of the code registers A and B, and closing at its armature and back contact a circuit extending through the upper left hand con-

tact of sequence switch cam 607 (4) for driving sequence switch 600 out of position 4 and into position 5. Upon leaving position 4 the initial energizing circuit extending through the left hand winding of relay 644 is opened at the contact of sequence switch 602 but is again established as soon as the sequence switch reaches position 5. Relay 644, upon re-energizing, closes a circuit for driving sequence switch 600 out of position 5 and into position 6, which circuit extends from battery through the winding of sequence switch magnet 600, the left hand contact of sequence switch cam 603 (5) and to ground at the armature and front contact of relay 644.

In position 6 sequence switch 600 again closes the circuit extending over sequence switch cam 604 and conductor 1101 and through the up drive magnet 1100 of translator switch TS. The up drive magnet is thereupon energized causing the movement of the selected sets of brushes of the translator switch over the selected group of terminals in the bank to which the selected sets of brushes have access, and until test brush 1104 engages a contact in the bank 1105 upon which ground potential has been placed by a circuit extending through the wiper of the code register C. Upon the engagement of the test brush 1104 with this terminal 1116, a circuit is established through the right hand winding of relay 644, which may be traced from grounded battery through the right hand winding of relay 644, the left hand contacts of sequence switch cam 605, conductor 1106, test brush 1104, terminal 1116, conductor 1117, contact 836 and wiper 837 of the code register C, which was set by the calling subscriber in response to the third code letter S in the same manner as registers A and B, thence over conductor 838 and to ground at the lower left hand contact of cam 609 (5 to 8) of the translator control sequence switch 600. The current flowing through the right hand winding of relay 644 now differentially balances the relay, causing its de-energization. Relay 644 upon de-energizing, opens at its armature and front contact the circuit extending through the up drive magnet 1100 of the translator switch TS, and at its armature and back contact closes a circuit extending through the magnet of sequence switch 600, and through the upper left hand contact of sequence switch cam 607 (6) for driving sequence switch 600 out of position 6 and into position 8. In passing out of position 6 the initial energizing circuit of relay 644 is opened at the contact of sequence switch cam 602, and in passing into position 7, a circuit is established for relays 1118 and 1119, which circuit may be traced from grounded battery through the windings of these relays in parallel, con-

ductor 1120, the right hand armature and back contact of relay 1121, conductor 1122 and thence to ground through the upper right hand contact of sequence switch cam 5 606 (7 to 14). Relays 1118 and 1119, upon energizing, connect the brushes of the brush sets 1112 and 1113 to the windings of translator register control relays 1000, 1001, 1002, 1003, 1004, and 1005.

10 During the setting of the translator switch TS and immediately following the setting of the code registers A, B and C, the calling subscriber has proceeded to dial the four numerical digits of the number 15 of the desired line causing the setting of the wipers of the thousands register TH upon the ninth set of contacts in the respective banks to which these wipers have access, the setting of the wipers of the hundreds register H upon the fifth set of contacts in the respective banks to which these wipers have access, the setting of the wipers of the tens register T upon the third set of contacts in the banks to which these wipers 20 have access and the setting of the wipers of the units register U upon the second set of contacts in the banks to which these wipers have access. Following the setting of the units register U, the register steering switch 25 RS moves its wipers to position 7 in which position a circuit is established for advancing the time measure switch TM from position 6 into position 16, this circuit extending from grounded battery through the 30 stepping magnet 626 of the time measure switch, wiper 627, the tied contacts of the bank with which this wiper is associated, interrupter 645, conductor 839, No. 7 contact 840 in the bank with which wiper 804 35 of steering switch RS is associated, wiper 804, conductor 803 and thence to ground through the make contacts of the right hand armature of relay 802.

40 *Setting the translator register relays.*

Upon the connection of the translator register relays 1000 to 1005 inclusive with the brushes of the brush sets 1112 and 1113 of the translator switch TS, impulses are 45 transmitted thereto from the pulse machine drum 1123. In the case assumed, two impulses are transmitted from grounded battery through the brush 1124, ring 1125, segments 1126, brush 1127, bank terminal 1128, brush 1129, conductor 1130, inner left hand armature and front contact of relay 1118, conductor 1131, thence to ground through the winding of class register control relay 1000. Similarly a circuit is established from 50 grounded battery through brush 1124, ring 1125, segment 1132, brush 1133, bank terminal 1134, brush 1135, conductor 1136, the inner right hand armature and front contact of relay 1118, conductor 1137 thence to ground through the winding of the district 55 brush register control relay 1001. A circuit is closed for office brush register control relay 1002 which may be traced from grounded battery through brush 1124, ring 1125, segment 1132, brush 1133, bank terminal 1140, 70 brush 1141, conductor 1142, the outer right hand armature and front contact of relay 1118, conductor 1143, and thence to ground through the winding of relay 1102. The circuit of the district group register control 75 relay 1003 may be traced from grounded battery through brush 1124, ring 1125, segment 1138, brush 1139, bank terminal 1144, brush 1145, conductor 1146, the inner left hand armature and front contact of relay 80 1119, conductor 1147 and thence to ground through the winding of relay 1003. The circuit of office group register control relay 1004 may be traced from grounded battery through brush 1124, ring 1125, segment 1132, brush 1133, bank terminal 1148, brush 1149, conductor 1150, the inner right hand armature and front contact of relay 1119, conductor 1151, and thence to ground through the winding of relay 1004. The talking selection register control relay 1005 is energized over a circuit extending from grounded battery through brush 1124, ring 1125, segment 1132, brush 1133, bank terminal 1152, brush 1153, conductor 1154, the outer right hand armature and front contact of relay 1119, conductor 1155, and thence to ground 85 through the winding of relay 1005.

90 Control relay 1000 upon energizing, closes a circuit for energizing relays 1006 and 1007 100 extending from grounded battery through the windings these relays in parallel and thence to ground through the armature and front contact of relay 1000, and the impulses received from the drum of the pulse machine by relay 1000 will thus be transmitted to the windings of relays 1006 and 1007. As soon as the pulse machine has rotated the drum 105 to a point where the brush 1127 engages the first segment 1126 and relays 1000, 1006 and 1007 are thus energized, a circuit will be 110 closed for the class register relay 1008 which circuit may be traced from grounded battery, through brush 1124, ring 1125, segment 1156, brush 1157, conductor 1158, the inner left hand armature and front contact of relay 1106, conductor 1009 and thence through the right hand winding of class 115 register relay 1008 to ground. This relay, upon energizing, closes a locking circuit for 120 itself extending from grounded battery through the upper left hand contact of sequence switch cam 610 (7 to 14), conductor 646, conductor 1010 and thence through the left hand armature and front contact and left hand winding of relay 1008 to ground. When the pulse machine drum rotates to a 125 position in which the second segment 1126 is engaged with brush 1127, a circuit is established for class register relay 1011 which 130

may be traced from grounded battery through brush 1124, ring 1125, segment 1159, brush 1160, conductor 1161, the outer left hand armature and front contact of relay 1006 and thence to ground through the left hand winding of relay 1011. Relay 1011, upon energizing, locks up through its right hand winding and armature and front contact to the locking conductor 1010 in the 10 same manner as relay 1008.

In view of the fact that the office to which the call is being extended is reached through both a district selector and an office selector switch the skip office register relay 1012 is 15 not energized at this time.

In a manner similar to that above described, the other register relays are variously set by the pulse machine through the operation of control relays 1001 to 1005 inclusive. The district brush register relay 1013 which was energized through the co-operation of control relay 1001 and pulse machine drum 1123, upon energizing closes a locking circuit for itself extending from 20 grounded battery through upper right hand contact of sequence switch cam 610 (7 to 13), conductor 647, thence to ground through the inner left hand armature and front contact and left hand winding of relay 1013. 25 The office brush register relay 1014 which was energized through the co-operation of control relay 1002 and the pulse machine drum, closes a locking circuit for itself extending to the battery lead 647, and the district group register relay 1015 and the office group register relay 1016 also close locking circuits for themselves, extending through their respective left hand windings and inner left hand armature contacts to the conductor 647. The talking selection register relay 1017 which was energized from impulses over a circuit extending from grounded battery through the brush 1124, segment 1156, brush 1157, conductor 1158, inner left 30 hand armature and front contact of relay 1018, conductor 1019 and thence to ground through the left hand winding of talking selection relay 1017, closes a locking circuit for itself through its right hand winding and inner right hand armature and front contact and thence to battery lead 646.

At the beginning of the transmission of impulses from the pulse machine to the translator register control relays, the translator control sequence switch being in position 8, a circuit is established from grounded battery through brush 1124, ring 1125, timing segments 1162 of the pulse machine, brush 1163, conductor 1164, right hand contacts of sequence switch cam 605 (8), resistance 648, conductor 649, winding of sender stepping relay 719, the armature and back contact of relay 720, the upper contacts of cam 706, conductor 736, the right contact of cam 612 (5 to 9) conductor 737,

and thence to ground through the contacts of cam 707 (1 to 4) and resistance 722. At this time a circuit is also closed for the No. 6 counting relay 723 extending from grounded battery through the winding of relay 723, the armature and back contact of upper No. 6 counting relay 724, lead 725, lead 725 Fig. 11, the outer left hand armature and front contact of relay 1119, conductor 1165, conductor 726, lower left hand and upper right hand contacts of sequence switch cam 702, the armature and front contact of stepping relay 719 and thence to ground through the lower left hand contact of sequence switch cam 703. In response to the first timing impulse through the stepping relay 719, the circuit just traced through counting relay 723 is closed and counting relay 723 energizes, closing a locking circuit for itself extending from grounded battery through its winding, the winding of upper counting relay 724, the armature and front contact of relay 723 and thence to ground over conductor 727 and the upper left hand contact of sequence switch cam 609 (8). Counting relay 724 does not energize in this locking circuit in view of the fact that its winding is shunted by ground connected to one terminal of its winding over lead 725 and through the front contact of stepping relay 719. As soon, however, as stepping relay 719 de-energizes following the transmission of the first timing impulse, the shunt is removed and relay 724 energizes, transferring the ground connected on lead 725 from the winding of counting relay 723 through the armature and front contact of counting relay 724, the armature and back contact of upper No. 5 counting relay 728 to grounded battery through the winding of lower No. 5 counting relay 729. In a similar manner counting relay 729 and the remaining counting relays of the series energize and lock up on succeeding impulses from the timing segments of the pulse machine, until the lower No. 0 counting relay 730 and the upper No. 0 counting relay 731 energize. At this time seven impulses have been counted out thus ensuring a complete revolution of the pulse machine drum for setting the translator register relays, before relay 731 by its energization initiates the movement of sender sequence switch 700 out of normal position 1 into position 2, in which position the fundamental circuit is closed for controlling the first selecting movement of the district selector 250.

Restoration of translator switch.

Upon the energization of counting relay 731, a circuit is closed for control relay 760 of the class switch which may be traced from grounded battery, through the right hand winding of relay 760, over conductor 900, through the left hand armature and front

contact of relay 1118, conductor 1166, and thence to ground at the armature and front contact of counting relay 731. Relay 760, upon energizing, closes a circuit for relay 1121, Fig. 11, which may be traced from grounded battery through the winding of relay 1121, conductor 1167 and thence to ground at the armature and front contact of relay 760. Relay 1121, upon energizing, 10 closes a locking circuit for itself extending through its right hand armature and front contact, over conductor 1122 and thence to ground through the upper right hand contact of translator control sequence switch 15 cam 606 (7 to 14). At its right hand armature and back contact relay 1121 opens the energizing circuit of relays 1118 and 1119 which thereupon de-energize, disconnecting the pulse machine from the windings of 20 translator register control relays 1000 to 1005 inclusive. Upon the de-energization of relay 1118, the circuit of relay 760 is opened and relay 760 thereupon de-energizes closing at its armature and back contact a circuit 25 for driving the translator control sequence switch 600 out of position 8 and into position 9. This circuit may be traced from grounded battery through the sequence switch magnet 600, right hand contact of 30 sequence cam 603 (8) conductor 652, the left hand armature and front contact of relay 1121, conductor 1168 and thence to ground at the armature and back contact of relay 760.

35 When the translator control sequence switch 600 reaches position 9 a circuit is established for releasing relay 1169 of the translator switch TS, which circuit may be traced from grounded battery through the right hand non-inductive winding of relay 1169, through the left hand winding of this relay, conductor 1170 and thence to ground through the lower right hand contact of sequence switch cam 608 (9 to 18). Relay 40 45 1169, upon energizing, closes a circuit for the down drive magnet 1171 of the translator switch TS, this circuit extending from grounded battery through the winding of the down drive magnet and thence to ground through the armature and front contact of relay 1169. The energization of magnet 1171 presses the depending portion of the switch shaft 1102 against the constantly rotating down drive roller 1172 thereby driving the switch shaft downwardly into its normal position. When the switch shaft 1102 reaches normal position, the off normal contacts 1173 become closed thereby connecting ground potential to the junction point between the right hand non-inductive and left hand winding of relay 1169, shunting out the energizing winding of this relay and causing the relay to de-energize.

50 During the restoration of the translator switch shaft 1102, the tripped brush sets are

again restored to their normal untripped positions in the well known manner. The translator switch TS and circuits associated therewith are now in normal condition in readiness for controlling subsequent calls. 70

Setting the class switch.

In position 9 of the translator control sequence switch 600 a circuit is also established for moving the sender sequence switch 700 out of position 1 and into position 2. This circuit may be traced from grounded battery the winding of the sender sequence switch magnet 700, conductor 732, the lower right hand contact of sequence switch cam 704 (1), conductor 733, the outer right hand armature and front contact of the energized district brush register relay 1013, the outer right hand armature and front contact of the energized office brush register relay 1014, the outer left hand armature and front contact of energized district group at district register relay 1015, the outer right hand armature and front contact of energized office group register relay 1016, the outer right hand and front contact of energized talking selection register relay 1017, and thence over conductor 1019 to ground through the lower right hand contact of translator control sequence switch cam 609 (8 $\frac{3}{4}$ to 9).

Upon the energization of class register relays 1008 and 1011 circuits were closed for driving the class switch 750 out of the position in which it was standing and into position 4, position 4 being the position assigned for all full mechanical calls. Assuming that the class switch 750 was standing in position 12 at the time class register relays 1008 and 1011 were energized, the circuits for driving the class switch out of position 12 and into position 4 are as follows: Switch 750 is driven from position 12 into position 14 100 over a circuit extending from grounded battery through the switch magnet 750, the lower right hand contact of switch cam 752 (6 to 13), conductor 901, the right hand armature and back contact of relay 1009, conductor 1020, conductor 1167, and thence to ground through the armature and front contact of relay 760 this relay having been energized as previously described, immediately following the transmission of impulses from the pulse machine drum for setting the translator register relays. Class switch 750, upon reaching position 14, is driven through position 18 into position 1 over a circuit extending from grounded battery, through the switch magnet winding 750, the upper left hand contact of cam 752, (13 to 18) conductor 902, the right hand armature and back contact of class register relay 1021, conductor 1020, thence to ground at the armature 105 110 115 120 125 130

and front contact of relay 760. Upon reaching position 1, the class switch is driven into position 3 over a circuit extending from grounded battery, through the magnet winding 750, the lower right hand contact of cam 753 (1 to 2), conductor 761, the right hand armature and front contact of class register relay 1008, conductor 1020 and thence to ground at the armature and front contact of relay 760. In position 3 a circuit is closed for driving class switch 750 into position 4 which circuit may be traced from grounded battery through the magnet winding 750, the upper left hand contact of cam 753 (3), conductor 762, the left hand armature and front contact of class register relay 1011, conductor 1020 and to ground at the armature and front contact of relay 760. Upon reaching position 4 no circuit is closed through armature contacts of the class register relays and therefore the class switch is arrested in position 4.

District brush selection.

25 The sender sequence switch 700 is now standing in position 2 and sequence switch 200 of the district selector 250 is in position 3. A fundamental circuit is now established from grounded battery through the 30 left hand winding of relay 228 of the district selector, the upper right hand and lower left hand contacts of sequence switch cam 210 (3), conductor 243, the inner right hand armature and front contact of cut-in relay 35 235, brush 244 of the sender finder switch SF and the contact of the bank with which this brush is associated, conductor 653, the left hand contact of translator control sequence switch cam 611, (9 to 12) conductor 40 654, the contact of sender sequence switch cam 705 (2), the left hand winding of polarized over-flow relay 734, conductor 735, the windings of sender stepping relay 719, the armature and back contact of relay 720, the 45 upper contacts of sender sequence switch cam 706, conductor 736, the right hand contacts of translator control sequence switch cam 612 (5 to 9), conductor 737, the contacts of sender sequence switch cam 707 50 (1 to 4) and thence to ground through resistance 722. Line relay 228 of the district selector switch and the stepping relay 719 of the office sender are energized in this circuit.

55 Relay 228, upon energizing, closes a circuit for driving sequence switch 200 of the district selector out of position 3 and into position 4. This circuit extends from grounded battery through the magnet winding of sequence switch 200, the upper left hand contact of sequence switch cam 206 (3), the inner right hand armature and front contact of relay 228 and thence to ground at the lower right hand contact of sequence switch cam 207 (1 to 6). A cir-

cuit is now established for relay 261 extending from battery through the winding of relay 261, upper contact of cam 216 (2 to 10), the outer right hand armature and contact of relay 233, the lower contact of cam 217 (3 to 10), wiper 262, conductor 655, the left hand armature and contact of relay 656 to ground at cam 614 (2 to 18). With the district sequence switch 200 in position 4 a circuit is also closed for the up drive magnet 245 of the district selector, which circuit extends from grounded battery through the winding of magnet 245, the upper right hand contact of sequence switch cam 209 (4), conductor 234, and thence to ground through the inner right hand armature and front contact of relay 228 and the lower right hand contact of sequence switch cam 207. Magnet 245, upon energizing, presses the depending portion of the switch shaft 246 against the constantly rotating up drive roller 247, thereby causing the upward movement of the switch shaft. Upon the movement of the sequence switch 200 out of position 3 the initial energizing circuit of relay 228, which extended through its left hand winding, and the upper right hand and lower left hand contacts of sequence switch cam 210 is opened at the upper right hand contact of this sequence switch cam, but a locking circuit for relay 228 is closed through its left hand armature and front contact, through the left hand contacts of sequence switch cam 210, and thence as traced over the fundamental circuit.

During the upward movement of switch shaft 246 of the district selector switch 250, ground potential is intermittently connected to the fundamental circuit at a point of junction between the winding of the stepping relay 719 of the office sender and the winding of line relay 228 of the district selector. This ground potential is connected to the junction point at sequence switch cam 210 over a circuit extending from sequence switch cam 210, through the upper contact of sequence switch cam 211 (3 $\frac{3}{4}$ to 4), conductor 248, brush selection segment 249 of the commutator 251, brush 252 carried upon the upper end of switch shaft 246, and thence to ground at the lower left hand contact of sequence switch cam 214 (9 to 7). The application of this intermittent ground potential to the fundamental circuit has no effect upon the energization of relay 228 of the district selector but causes the intermittent de-energization of the stepping relay 719 in synchronism with the upward movement of the district selector shaft 246.

Under the assumption that the district brush translator register relays have been so set by code impulses dialed by the calling subscriber as to energize only the dis-

trict brush relay 1013, a circuit is established upon the first energization of stepping relay 719 after the establishment of the fundamental circuit through relay 228, extending 5 from grounded battery through the lower No. 2 counting relay 737, the armature and back contact of upper No. 2 counting relay 738 lead 739, lead 739 Fig. 10, the inner right hand armature and front contact of the district brush register relay 1013, the right hand armature and back contact of district brush register relay 1022, conductor 1023, the lower right hand contact of sender sequence switch cam 708 (2), conductor 740, 10 the right hand contacts of translator control sequence switch cam 613 (9 to 12), conductor 741, conductor 726, the left hand contacts of sender sequence switch cam 702 (2), the armature and front contact of stepping relay 719, and to ground through the lower right hand contact of sequence switch cam 703. Counting relay 737, upon energizing, in this circuit, closes a locking circuit for itself extending from grounded battery through the winding of relay 737, the winding of upper counting relay 738, the armature and front contact of relay 737, conductor 742, and thence to ground through the upper right hand contact of sender sequence switch cam 703. The upper counting relay 738 does not energize at this time since its winding is shunted by a ground connected through the armature and contacts of stepping relay 719. Upon the first de-energization of relay 719, through the first connection of ground to the junction point 210 of the fundamental circuit by the commutator brush 252, relay 738 energizes transferring the connection of the control lead 40 739 from the winding of the lower No. 2 counting relay 737 to the winding of the lower No. 1 counting relay 743, this transferred circuit extending from lead 739 through the armature and front contact of the upper No. 2 counting relay 738, the armature and back contact of upper No. 1 counting relay 744, and thence to grounded battery through the winding of the lower No. 1 counting relay 743. Upon the second 45 de-energization of stepping relay 719, the No. 1 counting relay 744 becomes energized and transfers connection from control lead 739 to the lower No. 0 counting relay 730, and in response to the next de-energization of stepping relay 719, the upper No. 0 counting relay 731 is energized, closing a circuit for driving the sender sequence switch 700 out of position 2 and into position 4. This circuit may be traced from grounded battery through the winding of sequence switch magnet 700, through the upper left hand contact of sequence switch cam 704 (2) and thence to ground at the armature and front contact of upper counting relay 731. Sequence switch 700 upon leaving position 2, 50

opens the locking circuits of all counting relays which have been locked up, at the upper right hand contact of sequence switch cam 703.

At the time the upper No. 0 counting relay 731 energized in response to the last de-energization of stepping relay 719, relay 720 was energized in parallel therewith, opening at its armature and back contact the fundamental circuit previously traced extending through the windings of stepping relay 719 and line relay 228 of the district selector 250. The circuit of relay 228 now being open, relay 228 de-energizes closing a circuit for driving the district selector sequence switch 200 out of position 4 and into position 5. This circuit extends from grounded battery through the winding of sequence switch magnet 200, the upper right hand contact of sequence switch cam 206 (4), the inner right hand armature and back contact of relay 228 and thence to ground at the lower right hand contact of sequence switch cam 207. As soon as relay 228 de-energizes, the circuit previously traced through the up drive magnet 245 is opened at the inner right hand armature and back contact of relay 228. With sequence switch 200 of the district selector in position 5 and the sender sequence switch 700 in position 4, the fundamental circuit previously traced is again established, and relay 228 of the district selector and stepping relay 719 of the sender energize. Relay 228, upon energizing, causes the movement of the district selector sequence switch 200 from position 5 into position 6. As soon as sequence switch 200 leaves position 5, the initial energizing circuit of relay 228, which was closed over the fundamental circuit through the upper right hand contact of sequence switch cam 210 (5) and the lower left hand contact of cam 210 (3 to 6) is opened, but relay 228 locks up through its left hand winding, its left hand armature and front contact and the left hand contacts of sequence switch cam 210. 55

District group selection.

Upon reaching position 6, the circuit previously traced for the up drive magnet 245 is again established through the upper right hand contact of sequence switch cam 209 (6), and the inner right hand armature and front contact of relay 228, and in the manner previously described the switch shaft 246 is again driven upwardly. Since at this time however, the tripping spindle 292 has been rotated by the tripping magnet 253, which was energized in position 5 of sequence switch 200 over a circuit extending from grounded battery through the winding of magnet 253 and to ground through the lower right hand contact of sequence switch cam 208 (5 to 7), the third set of brushes is 60 65 70 75 80 85 90 95 100 105 110 115 120 125 130

- now tripped upon the initial upward movement of the switch shaft 246, and during the continued upward movement of the switch shaft, the brushes travel over the contacts of the bank with which they are associated. The remaining four sets of brushes on the switch shaft are not tripped at this time and therefore are functionless. During the upward movement of the switch shaft an intermittent ground is connected to the junction point (sequence switch cam 210) in the fundamental circuit between the winding of relay 228 and the winding of stepping relay 219, over a circuit extending over the lower right hand contact of sequence switch 210 (5 $\frac{1}{4}$ to 6), conductor 254, group selecting commutator segment 255, shaft brush 256, and thence to ground at the lower left hand contact of sequence switch cam 214 (9 to 7). As before described, the intermittent connection of ground to the junction point of the fundamental circuit causes the intermittent de-energization of stepping relay 719 of the sender. In this case, however the commutator segment 255 is so designed as to cause the de-energization of stepping magnet 719 upon the positioning of the selected set of brushes beneath each of the groups of terminals in the bank to which the selected set of brushes has access.
- Upon the first energization of stepping relay 719 over the fundamental circuit above traced, a circuit is closed for the No. 0 counting relay 730, which circuit may be traced from grounded battery through the winding of No. 0 counting relay 730, contact of sequence switch spring 709, lead 745, lead 745 Fig. 10, the outer left hand armature and back contact of district group register relay 1024, the outer left hand armature and back contact of district group register relay 1025, the right hand armature and front contact of district group register relay 1015, conductor 1026, the upper left hand contact of sender sequence switch cam 708 (4), conductor 740, the right hand contact of translator control sequence switch cam 613 (9 to 12), conductor 741, the lower left hand and upper right hand contacts of sequence switch cam 702, contacts of relay 719, and thence to ground through the lower left hand contact of sequence switch cam 703. Counting relay 730, upon energizing in this circuit, closes a locking circuit for itself extending through the winding of upper No. 0 counting relay 731, through the armature and front contact of relay 730 and thence to ground over conductor 742 and the upper right hand contact of sender sequence switch cam 703. The upper counting relay 731 does not energize at this time since its winding is shunted by ground connected to the circuit extending through the armature and contacts of stepping relay 719. When relay

719 de-energizes, upon the movement of the switch shaft 246 of the district selector positioning the tripped set of brushes beneath the first group of contacts in the bank to which it has access, relay 731 becomes energized closing at its armature and front contact a circuit as previously traced through the upper left hand contact of sequence switch cam 704 for driving sequence switch 700 out of position 4 and into position 6. Upon leaving position 4, the locking circuit extending through the windings of relays 730 and 731 is opened at sequence switch cam 703. Relay 720, which energized in parallel with the upper counting relay 731, opens the fundamental circuit at its armature and back contact thereby causing the de-energization of line relay 228 of the district selector.

Relay 228, upon de-energizing, opens at its inner right hand armature and front contact the circuit previously traced extending through the up drive magnet 245, thereby arresting the upward movement of the switch shaft for positioning the tripped set of brushes beneath the proper group of terminals in the bank. At its inner right hand armature and back contact, relay 228 closes a circuit extending through the upper right hand contact of sequence switch cam 206 for driving sequence switch 200 out of position 6 and into position 7. In position 7, relay 228 energizes over a circuit extending from grounded battery through its right hand winding, the lower right hand contact of sequence switch spring 204 (7), conductor 229, the lower contacts of sequence switch cam 205 and to ground at the right hand armature and front contact of sleeve relay 226. Relay 228, upon energizing, closes a circuit for driving sequence switch 200 out of position 7 and into position 8. This circuit may be traced from grounded battery through the magnet winding of the sequence switch, conductor 231, the upper left hand contact of sequence switch cam 206 (7), the inner right hand armature and front contact of relay 228, the upper right hand contact of sequence switch cam 207 (7 to 8); and thence to ground through the make contacts of the right hand armature of relay 227.

As soon as sequence switch 200 leaves position 7, the initial energizing circuit of relay 228 is opened at sequence switch cam 204 but relay 228 locks up over a circuit extending from grounded battery through its left hand winding, its left hand armature and front contact, the left hand contacts of sequence switch cam 215, the outer right hand armature of relay 228 through the lower contacts of cam 222, test brush 257 and, if the first trunk of the selected group is busy, to ground at the test terminal of the trunk. Upon reaching position 8, with re-

lay 228 energized, a circuit is established for the up drive magnet 245 which may be traced from grounded battery through the magnet 245, the upper right hand contact 5 of sequence switch cam 209 (8), the inner right hand armature and front contact of relay 228 and to ground at the lower right hand contact of sequence switch cam 207. The up drive magnet 245, upon energizing, 10 again drives the switch shaft upwardly in search of an idle trunk in the selected group. So long as the test brush encounters the terminals of busy trunks the relay 228 remains locked up. When, however, an idle 15 trunk is encountered which, it will be assumed is the trunk terminating in terminals 258, 259 and 260, the locking circuit of relay 228 is opened and relay 228 de-energizes as soon as the brushes 257, 263 and 264 have 20 been properly centered on the bank terminals 258, 259 and 260. Until the brushes are so centered, relay 228 remains locked up over a circuit extending through its right hand winding, the lower left hand contact 25 of sequence switch cam 204 (8), conductor 286, centering commutator segment 287, brush 288, lower left hand contact of sequence switch cam 209 (8), conductor 234, inner right hand armature and front contact of relay 228 to ground at the lower right hand contact of sequence switch cam 207.

It will be noted that during brush and group selection movements of the switch shaft, that commutator brushes 252 and 256 were connected to ground directly at the lower contact of sequence switch cam 214, but that during the trunk hunting movement the commutator brush 288 is grounded 35 through the inner right hand armature and front contact of relay 228. It is necessary to remove ground from brush 288 as soon as brush 288 engages the insulated portion 40 of segment 287 corresponding to an idle trunk in order to prevent relay 228 from remaining locked up and continuing the up drive of the switch shaft, should the switch brushes overrun an idle set of trunk terminals and position commutator brush 288 45 on the conducting portion of the segment 287 immediately above the insulated portion corresponding to an idle trunk. Since relay 228 de-energizes as soon as brush 288 engages the insulated portion of the segment, 50 this ground is removed at once from the brush 288 and prevents false hunting. Upon de-energizing, the circuit of the up drive magnet 245 is opened at the inner right hand armature and front contact of relay 55 228 thereby arresting the upward movement of the switch shaft 246, and a circuit is closed at the inner right hand armature and back contact of relay 228 for driving sequence switch 200 out of position 8 and into posi-

tion 9. Upon reaching position 8₁ busy 65 ground potential is connected to the multiple test terminals of the selected trunk over brush 257, commutator brush 290 segment 291 and the right hand contacts of cam 215.

Relay 228 again energizes when sequence 70 switch 200 reaches position 9, over a circuit extending through its right hand winding, the lower right hand contact of sequence switch cam 204 (9 to 10), conductor 229, the lower left hand and upper right hand 75 contacts of sequence switch cam 205 and to ground at the right hand armature and front contact of message registering relay 261. Relay 261 is at this time energized as previously described. 80

Relay 228, upon energizing in the circuit previously traced, closes a circuit through its inner right hand armature and front contact for driving sequence switch 200 out of position 9 and into position 10, in which 85 position the fundamental circuit is extended through contacts of sequence switch cams 218 and 219, through brushes 263 and 264 of the district selector switch to the line relay of the office selector switch 350. This 90 fundamental circuit may be traced from grounded battery through the right hand winding of relay 312, the lower contacts of sequence switch cam 302, the upper trunk conductor 313, bank terminal 260, switch 95 brush 263, the upper right hand and lower left hand contacts of sequence switch cam 218, conductor 264, conductor 243, the inner right hand armature and front contact of relay 235, wiper 244 of the sender selector 100 switch SF, conductor 653, the left hand contact of translator control sequence switch 611 (9 to 12), conductor 654, the contact of sender sequence switch cam 705 (6), the left hand winding of relay 734, conductor 105 735, the winding of stepping relay 719, the armature and back contact of relay 720, the right hand winding of relay 734, the winding of relay 746, conductor 747, the lower right hand and upper right hand contacts 110 of sequence switch cam 706, conductor 736, conductor 657, the lower contact of sequence switch cam 615 (9 to 12), the left hand armature and back contact of advance relay 658, conductor 659, brush 265 of the sender 115 finder SF, conductor 266, the lower left hand and upper right hand contacts of sequence switch cam 219, switch brush 264, bank terminal 259, trunk conductor 314, and thence to ground through the left hand 120 contact of sequence switch cam 303.

Office brush selection.

Relay 312 associated with the office selector switch 350 and the sender stepping relay 125 719 energize in this circuit. Relay 312 upon energizing, closes a circuit for driving sequence switch 300 out of its normal

position 1 and into position 2, this circuit extending from grounded battery through the magnet winding 300, the upper left hand contact of sequence switch cam 304 (1), conductor 315 and to ground through the left hand armature and front contact of relay 312. Sequence switch 300, on leaving position 1, opens the initial energizing circuit of relay 312 extending over the fundamental circuit as previously traced, but relay 312 locks itself over the fundamental circuit through its right hand winding, its inner right hand armature and front contact, and the upper left hand contact of sequence switch cam 305 (1 to 4). When the sequence switch 300 reaches position 2 a circuit is closed for the up drive magnet 316 which may be traced from grounded battery through the winding of this magnet, the upper right hand contact of sequence switch cam 304 (2), conductor 315 and thence to ground at the left hand armature and front contact of relay 312. Magnet 316, upon energizing, presses the depending portion of the switch shaft 317 against the constantly rotating up drive roller 318 and thereby causes the upward movement of the switch shaft. During this movement an intermittent ground is connected to the fundamental circuit at a junction point between the winding of relay 312 and the windings of the sender stepping relay 719, over a circuit which may be traced from the junction point (sequence switch cam 302) through the upper right hand contact of this sequence switch cam closed in positions 1 $\frac{1}{2}$ to 2, conductor 319, brush selection segment 320 of the commutator 321, brush 322, conductor 323 and thence to ground at the lower left hand contact of sequence switch cam 306.

The office sender relay 746 energizes over the fundamental circuit and at its armature and front contact closes a circuit for relay 748, which in turn closes a circuit for driving the sequence switch 700 out of position 6 and into position 8, this circuit extending from grounded battery through the magnet winding of sequence switch 700, conductor 732, the upper right hand contact of sequence switch cam 704 (6), and to ground at the outer left hand armature and front contact of relay 748. With the sender sequence switch in position 8 and the sender stepping relay 719 energized over the fundamental circuit previously traced, a circuit is closed for the No. 2 counting relay which may be traced from grounded battery through the winding of the No. 2 counting relay 737, the armature and back contact of upper No. 2 counting relay 738, lead 739, the inner right hand armature and front contact of office brush register relay 1014, the right hand armature and back contact of office

brush register relay 1027, conductor 1028, 65 the lower left hand contact of sequence switch cam 708 (8), conductor 740, the right hand contacts of translator control sequence switch cam 613, conductor 741, conductor 726, the lower left hand and upper right 70 hand contacts of sequence switch cam 702, armature contacts of stepping relay 719 and thence to ground through the lower left hand contact of sequence switch cam 703. In the manner previously described, the 75 counting relays are successively energized upon the successive energization and de-energizations of the stepping relay 719, through the connection of the intermittent shunting circuit at the office selector switch 80 until the upper No. 0 counting relay 731 energizes, when a circuit is closed for driving sequence switch 700 out of position 8 and into position 10. Relay 720 energizes in parallel with relay 731 and opens the fundamental circuit. 85

Upon the opening of the fundamental circuit relay 312 at the office selector switch de-energizes, opening at its left hand armature and front contact the circuit previously 90 traced through the winding of the up drive magnet 316 for arresting the upward movement of the switch shaft, and at its left hand armature and back contact closes a circuit for driving sequence switch 300 out of position 2 and into position 3. This circuit may be traced from grounded battery through the winding of sequence switch 300, conductor 324, the lower left hand contact of sequence switch cam 307 (2), conductor 325, 100 thence to ground at the left hand armature and back contact of relay 312. The switch shaft of the office selector has now moved upwardly to position the third set of brushes in a position to be tripped upon a subsequent upward movement of the switch shaft. 105 In position 3 of sequence switch 300 a circuit is closed for the tripping magnet 326 for tripping the selected set of brushes, over a circuit which may be traced from grounded 110 battery through the winding of tripping magnet 326 and to ground through the upper right hand contact of sequence switch cam 308 (3 to 4). 115

Office group selection.

With sequence switch 300 in position 3 and sender sequence switch 700 in position 10, the fundamental circuit previously 120 traced is again closed and relay 312 of the office selector and stepping relay 719 of the office sender again energize. Relay 312 upon energizing closes the circuit previously traced extending through the upper left hand contact of sequence switch cam 304 for 125 driving sequence switch 300 out of position 3 and into position 4. Upon leaving position 3 the initial energizing circuit of relay

312 is opened, but relay 312 remains energized over the locking circuit previously traced, extending through the left hand contact of sequence switch cam 305. Sequence switch 300 upon reaching position 4, again closes the circuit of the up drive magnet 316, which upon energizing, drives switch shaft 317 upwardly. During the initial upward movement of the switch shaft the selected set of brushes, in this instance the third set of brushes, is tripped and the brushes thereafter wipe over the terminals of the bank to which they have access upon the continued upward movement of the switch shaft. During the upward movement of the switch shaft an intermittent ground is connected to the junction point (sequence switch cam 302) in the fundamental circuit between the winding of relay 312 and the windings of stepping relay 719, which ground connection extends from cam 302 over the upper left hand contact of this cam (closed in position 3 $\frac{3}{4}$ to 4), conductor 327, group selection commutator segment 328, brush 329 and thence over conductor 323 to ground at the lower left hand contact of sequence switch cam 306 (7 to 5).

Upon the first closure of the fundamental circuit, with sequence switch 700 in position 10, the sender stepping relay 719 energizes, establishing a circuit for the No. 2 counting relay 737, which circuit may be traced from grounded battery through the winding of relay 737, the armature and back contact of relay 738, lead 739, the inner right hand armature and front contact of office group register relay 1016, the right hand armature and back contact of office group register relay 1029, conductor 1030, the upper right hand contact of sequence switch cam 708 (10), conductor 740 and thence over the circuit previously traced to ground at sequence switch cam 703. In the manner previously described, the counting relays successively energize through the operation of stepping relay 719 until the upper No. 0 counting relay 731 energizes, when a circuit, as previously described, is established through the upper left hand contact of sequence switch cam 704 (10) for driving the sequence switch 700 out of position 10 and into position 12. Upon leaving position 10 the locked-up counting relays become de-energized through the opening of the upper contact of sequence switch cam 703 as previously described. Relay 720 energizes in parallel with relay 731 and at its armature and back contact opens the fundamental circuit previously traced through the winding of relay 312 of the office selector switch and this relay, upon de-energizing, opens the circuit of the up drive magnet 316 at its left hand armature and front contact and at its left hand armature and back contact closes a circuit ex-

tending from the lower left hand contact of sequence switch cam 307 (4) for driving sequence switch 300 out of position 4 and into position 5.

Upon reaching position 5 sequence switch 300 closes a local circuit for the relay 312 which may be traced from grounded battery through the left hand winding of relay 312 and to ground through the lower contacts of sequence switch cam 303. Relay 312, upon energizing, closes a locking circuit for itself extending from its right hand winding, through the right hand armature and front contacts of the relay, the lower contact of sequence switch cam 309 (5 to 6) test brush 330 and to ground on the test terminal of the first trunk of the group to which the selected set of brushes has been moved if this trunk is at the time busy. Relay 312, upon energizing, also closes a circuit extending through the upper left hand contact of sequence switch cam 304 (5) for driving sequence switch 300 out of position 5 and into position 6. Upon leaving position 5 the initial energizing circuit of relay 312 is opened at cam 303, but relay 312 still remains energized over its locking circuit providing the first trunk in the selected group is busy.

As soon as sequence switch 300 reaches position 6 a circuit is closed for the up drive magnet 316, which upon energizing causes the selected set of brushes to be driven upwardly over the selected group of trunk terminals to which it has access. As soon as the test brush 330 engages the test terminal of an idle trunk, which it will be assumed is the trunk shown in the drawing, relay 312 de-energizes opening at its left hand armature and front contact the circuit of the up drive magnet 316 thereby arresting the upward movement of the switch shaft. Relay 312 does not de-energize however until the brushes of the switch have been centered upon the terminals of the idle trunk since it is held energized over a circuit extending from grounded battery through its left hand winding, the right hand contacts of sequence switch cam 303, centering segment 331 of the commutator 321, brush 332, conductor 323, the lower left hand contact of sequence switch cam 304, conductor 315 and thence to ground at the left hand armature and front contact of relay 312.

Relay 312, upon de-energizing, closes a circuit extending from its left hand armature and back contact over conductor 325 and the lower left hand contact of sequence switch cam 307 (6) for driving sequence switch 300 out of position 6 and into position 7. Upon reaching position 7 relay 312 is again energized over a circuit extending through its left hand winding and the lower contacts of sequence switch cam 303 and,

upon energizing closes a locking circuit for itself extending from grounded battery through its right hand winding, its inner right hand armature and front contact, the lower right hand contact of sequence switch cam 305 and thence to ground at the lower left hand contact of sequence switch cam 308 (2 to 7½). As soon as sequence switch 300 leaves position 7½ relay 312 is held energized over a circuit extending over sleeve conductor 333, test terminal 258 at the district selector switch, test wiper 257 in contact therewith, and thence to ground through the right hand contacts of sequence switch cam 215. The ground connected to sleeve conductor 333 also places a busy potential upon the test terminal 344, upon which the test brush 330 of the office selector switch is arrested, over a circuit extending through the right hand contacts of sequence switch cam 305. Relay 312, upon energizing, also closes a circuit for driving sequence switch 300 out of position 7 and into position 8, in which position the fundamental circuit is extended through contacts of sequence switch cams 310 and 311, switch brushes 334 and 335, bank terminals 336 and 337 to the trunk conductors 419 and 420 extending to the selected incoming selector 450. As soon as the fundamental circuit is extended to the incoming selector a circuit is closed from grounded battery through the right hand winding of relay 421, conductor 422, upper contacts of sequence switch cam 402, conductor 423, resistance 424, the upper contact of sequence switch cam 403 (1 to 10), trunk conductor 419 and thence over the fundamental circuit previously traced through the windings of sender stepping relay 719 and the winding of relay 746, back over trunk conductor 420, the lower contact of sequence switch cam 404 (1 to 10), resistance 425, conductor 426 and thence to ground through the lower contact of sequence switch cam 405 (1 to 8). Relay 421 energizes in this circuit and at its left hand armature and front contact closes a circuit for driving sequence switch 400 out of its normal position 1 and into position 2, this circuit extending from grounded battery through the winding of magnet 400, the lower right hand contact of sequence switch cam 406 (1), the outer left hand armature and front contact of relay 421, conductor 427 and thence to ground at the lower contact of sequence switch cam 407 (1 to 10). As soon as sequence switch 400 leaves position 1 the initial energizing circuit of relay 421 is opened at the upper left hand contact of sequence switch cam 402 but relay 421 remains energized over the fundamental circuit through a locking branch of the fundamental circuit which may be traced from grounded battery through the right hand winding of relay 421, the right hand

contacts of sequence switch cam 402, conductor 428, the right hand armature and front contact of relay 421, conductor 429, the left hand contacts of sequence switch cam 408 (1 to 4) and thence over the fundamental circuit as previously traced. 70

Incoming brush selection.

In position 2 of sequence switch 400 a circuit is closed for the up drive magnet 430 75 which may be traced from grounded battery through the winding of this magnet, the upper right hand contact of sequence switch cam 409 (2), conductor 431, outer left hand armature and front contact of relay 421, and thence to ground at the lower contact of sequence switch cam 407. Magnet 430, upon energizing, presses the depending portion of the switch shaft 432 against the constantly 80 rotating up drive roller 433 causing thereby the upward movement of the switch shaft. During the upward movement of the switch shaft an intermittent ground is connected to a junction point between the winding of relay 421 of the incoming selector switch and the windings of stepping relay 719 of the office sender, which intermittent ground is connected over a circuit extending from the junction point (sequence switch cam 408), through the lower right hand contact of this sequence switch cam closed in positions 1 85 to 2, brush selection segment 434 of the switch commutator 435, brush 436, conductor 437 and thence to ground through the lower contact of sequence switch cam 410 (7 to 5). 90

Upon the establishment of the fundamental circuit through the windings of sender stepping relay 719 and the winding of relay 746, these relays energize and relay 746 closes the circuit previously traced extending through the winding of relay 748. Relay 748 upon energizing closes a circuit extending through the upper right hand contact of sender sequence switch cam 704 (12) for driving sequence switch 700 out of position 105 12 and into position 14. Sequence switch 700, upon reaching position 14, closes a circuit for relay 749 which circuit extends from grounded battery through the winding of relay 749 and thence to ground through the right hand contacts of sender sequence switch cam 710 (14). Relay 749, upon energizing, closes a circuit driving the sender sequence switch 700 out of position 14 and into position 16. This circuit may be traced through the magnet winding of sequence switch 700, conductor 763, the upper contacts of translator control sequence switch cam 616, conductor 764, armature and front contact of relay 749 and thence to ground 110 through the lower contacts of class switch cam 754 (4); it being remembered that the class switch was set in position 4 for the establishment of a full mechanical call. 115

With the sender sequence switch 700 in 120

position 16 and relay 719 energized over the fundamental circuit as previously traced through the winding of relay 421 of the incoming selector switch, and assuming that 5 the calling subscriber has dialed the thousands digit nine, a circuit is closed upon the first energization of stepping relay 719, for the No. 4 counting relay 764, this circuit extending from grounded battery through 10 the winding of the lower No. 4 counting relay 764, the armature and back contact of the upper No. 4 counting relay 765, lead 766, lead 766 Fig. 9, connected to the No. 9 contact 903 of the thousands register TH, wiper 15 904 which has been positioned in engagement with this contact, conductor 905, the lower left hand contact of sequence switch cam 711 (16), conductor 740, and thence over the circuit previously traced to ground at the 20 contact of sequence switch cam 703. Counting relay 764, upon energizing, closes a locking circuit for itself extending through the winding of the upper counting relay 765 in the manner previously described and relay 25 765 becomes energized in this locking circuit as soon as stepping relay 719 de-energizes upon the first upward step of the incoming selector switch shaft 432. In the manner previously described, the counting relays 764, 30 768, 737, 743 and 730 energize in succession. When the upper No. 0 counting relay 731 energizes in the locking circuit of relay 730 it closes a circuit for driving sequence switch 700 out of position 16 and into position 17. 35 This circuit extends through the winding of magnet 700, conductor 732, the lower left hand and upper right hand contacts of sequence switch cam 712 (16), the right hand contacts of translator control sequence 40 switch cam 617 (9 to 12) and thence to ground at the armature and front contact of counting relay 731. Relay 720 energizes in parallel with counting relay 731 opening the fundamental circuit thereby causing the de- 45 energization of relay 421 at the incoming selector switch.

With sequence switch 700 in position 17, relay 719 energizes over a local circuit extending from battery through the winding 50 of relay 749, the right hand contacts of cam 717 (17), the left hand winding of relay 734, conductor 735, the windings of relay 719, the armature and back contact of relay 720, the left hand contacts of cam 706 (17) and thence to ground through resistance element 55 722. Relay 719 energizes and closes a circuit for driving sequence switch 700 out of position 17 into position 18, this circuit extending from battery through the lower right hand and upper left hand contacts of cam 702, armature and contacts of relay 719 and thence to ground through the lower right hand contact of cam 703.

Relay 421, upon de-energizing, opens at 60 its outer left hand armature and front contact, the circuit, of the up drive magnet 430 thereby arresting the upward movement of the switch shaft 432, and at its inner left hand armature and back contact closes a circuit for driving sequence switch 400 out of position 2 and into position 3, this circuit extending from grounded battery through the magnet winding 400, the upper left hand contact of sequence switch cam 406 (2) and thence to ground at the inner left hand armature and back contact of relay 421. Upon reaching position 3 sequence switch 400 closes a circuit for the trip magnet 438, extending from grounded battery through the magnet winding 438 and thence to ground 65 through the right hand contact of sequence switch cam 405 (3 to 4). Trip magnet 438, upon energizing, rotates the tripping spindle 439 into such a position as will trip the selected set of brushes which, in the case assumed, is the fifth set of brushes, upon the subsequent upward movement of the switch shaft 432.

Incoming group selection.

Upon reaching position 3 the fundamental circuit extending through the winding of relay 421 and windings of stepping relay 719 is again established over the circuit previously traced. Relay 421, upon energizing in this circuit, again closes the circuit previously traced for driving the sequence switch 400 out of position 3 into position 4, and at its right hand armature and front contact closes the locking circuit previously traced for holding itself energized over the fundamental circuit after sequence switch 400 leaves position 3. With sequence switch 400 in position 4 and relay 421 energized, the circuit previously traced through the up drive magnet 430 is again closed and the switch shaft 432 is again driven upwardly. During the initial upward travel of the switch shaft the fifth set of brushes is tripped by the tripping spindle 439 and during subsequent upward movements of the switch shaft the tripped set of brushes travels in engagement with the terminals of the bank with which it is associated. During the upward movement of the switch shaft, an intermittent ground is connected to the junction point (sequence switch cam 408) in the fundamental circuit between the winding of relay 421 and the winding of the sender stepping relay 719, over a circuit extending from the upper right hand contact of cam 408 (3 to 4) through group selection segment 440 of commutator 435, brush 441, and thence to ground over conductor 437 and the lower contact of sequence switch 410. 110

The energization of the sender stepping relay with sequence switch 700 in position 18 closes a circuit for the No. 2 counting relay 737, assuming that the calling subscriber has dialed the second digit No. 5, which may be 115 120 125 130

traced from grounded battery through the winding of the lower No. 2 counting relay 737 the armature and back contact of the upper No. 2 counting relay 738, lead 739 and thence to lead 906 Fig. 9, the right hand armature and back contact of relay 907, which relay is not energized at this time since it is assumed that the hundreds digit of the desired line was 5 and wiper 931 of hundreds register H is positioned in the first half of its bank of terminal contacts, No. 9 contact 908 of the thousands register TH, wiper 909, which has been positioned in engagement therewith, conductor 910, the lower right hand contact of sequence switch cam 711 (18), conductor 740 and thence over the circuit previously traced to ground at sequence switch cam 703. Counting relay 737 energizes in this circuit and locks up in the manner previously described through the winding of counting relay 738, which relay 738 energizes on the first de-energization of stepping relay 719. In the well-known manner, counting relays 743 and 730 are successively energized and when the upper No. 0 counting relay 731 energizes upon the third de-energization of stepping relay 719, or at the time the tripped set of brushes at the incoming selector switch have been positioned beneath the third group of terminals in the bank to which they have access, it closes a circuit at its armature and front contact for driving the translator control sequence switch 600 out of position 12 and into position 13. This sequence switch was moved out of position 9 and into position 12 over a circuit closed in position 18 of the sender sequence switch 700, which circuit extends from grounded battery through the magnet winding of sequence switch 600, the upper right hand contact of sequence switch cam 607 (9 to 10), conductor 660 and thence to ground through upper left hand contact of sequence switch cam 713. The circuit for driving translator control sequence switch 600 out of position 12 into position 13 may be traced from grounded battery through the magnet winding 600, the lower right hand contact of sequence switch cam 607 (12), conductor 661, the right hand contacts of sequence switch cam 714 (18) and thence to ground at the armature and front contact of relay 731. The purpose of driving the translator control sequence switch into position 13 at this time is to prepare circuits for permitting a second rotation of sequence switch 700 for controlling the circuits of the sender during the final brush, final group, and units selection movements of the final selector switch, and the talking selection movement of the sequence switch 200 of the district selector. With the translator control sequence switch in position 13 a circuit is now closed for driving the sender sequence switch 700 out

of position 18 and into position 1, this circuit extending from grounded battery through the magnet winding 700, conductor 732, conductor 769, the right hand contacts of sequence switch cam 618 (13), conductor 70660 and thence to ground through the upper left hand contact of sequence switch cam 713. Upon reaching position 1, a circuit is closed over conductor 733 and the lower right hand contact of sequence switch cam 704, as previously described, for driving sequence switch 700 out of position 1 and into position 2, in which position the circuits of the sender are in condition for controlling brush selection at the final selector switch.

At the time counting relay 731 energizes upon completion of group selection at the incoming selector switch, relay 720 energizes in parallel therewith and at its armature and contact opens the fundamental circuit extending through line relay 421 of the incoming selector switch. This relay upon de-energizing opens the circuit previously traced through the up drive magnet 430 thereby arresting the upward movement of the switch shaft. At its inner left hand armature and back contact relay 421 closes a circuit extending through the winding of sequence switch magnet 400 and the upper left hand contact of sequence switch cam 406 (4) for driving the sequence switch out of position 4 and into position 5. In position 5 relay 421 is again energized by a circuit extending from grounded battery through its left hand winding and thence to ground through the right hand contacts of sequence switch cam 411. Relay 421 now closes a circuit extending from ground at sequence switch cam 407 and through the outer left hand armature and front contact of relay 421 for driving sequence switch 400 out of position 5 and into position 6. Upon leaving position 5 the initial energizing circuit extending through the winding of relay 421 is opened at sequence switch cam 411, but relay 421 remains energized over a locking circuit extending from grounded battery through its right hand winding, the right hand contacts of sequence switch cam 402, conductor 428, the right hand armature and front contact of relay 421, conductor 429, the right hand contacts of sequence switch cam 412 and thence through test brush 442 to ground on the test terminal of the first trunk of the group to which the brush set has been moved during the group selection movement of the switch shaft, if the first trunk of the group is at the time busy.

When sequence switch 400 reaches position 6 a circuit is closed for the up drive magnet 430 over the circuit previously traced, for driving the switch shaft upwardly in its trunk hunting movement.

This movement will continue so long as the test brush 442 encounters ground potential on the test terminals of the trunks of the group over which this brush moves. When, however, an idle trunk is found which it will be assumed is the trunk disclosed, the locking circuit of relay 421 will be opened and since the initial energizing circuit of relay 421 was opened as soon as the sequence switch moved out of position 51, relay 421 will de-energize thereby opening at its outer left hand armature and front contact the circuit of the up drive magnet 430. To ensure, however, that the brushes shall be properly centered on the terminals of the selected idle trunk, relay 421 is maintained energized to maintain the circuit of the up drive magnet 430 until the brushes are so centered, by an additional locking circuit extending from grounded battery through the left hand winding of relay 421, the upper right hand and lower left hand contacts of sequence switch cam 411, conductor 443, centering commutator segment 444, brush 445, conductor 437, the upper left hand contact of sequence switch cam 410 (6), conductor 431, the outer left hand armature and front contact of relay 421 and thence to ground through the sequence switch cam 407. It is to be noted in this connection that during the trunk hunting movement of the switch shaft, the circuit extending through commutator segment 444 leads through a front contact of relay 421 rather than directly to ground at the sequence switch cam 410 in order to prevent the continuation of the upward movement of the switch shaft 432 should the switch shaft over-run and carry the set of brushes past the terminals of an idle trunk. It is to be noted that as soon as the shaft brush 445 engages an insulating section of the segment 444 corresponding to the first idle trunk the circuit of relay 421 is opened and this relay immediately de-energizes opening the circuit through the shaft brush 445 and commutator 444 before the brush 445 can engage the conducting portion of commutator 444. Therefore, upon such over run, relay 421 being de-energized, the up drive magnet 430 does not continue the upward movement of the switch shaft.

Upon the de-energization of relay 421, following the centering of the brushes of the switch upon the terminals of the selected idle trunk, the circuit previously traced is closed for driving the sequence switch 400 out of position 6 and into position 7. In position 7 relay 421 again energizes in a circuit extending through its left hand winding and the right hand contacts of sequence switch cam 411 and closes a circuit for driving the sequence switch out of position 7 and into position 8. The fundamental circuit may now be

traced from battery through the left hand contact of cam 504 (1 to 10), the right hand winding of relay 518, the lower left hand contact of cam 503 (1), the lower left hand contact of cam 502 (15 to 6), conductor 517, bank terminal 447 and brush 446 of selector switch 450, the upper left hand contact of cam 413 (8), the upper contact of cam 403 (1 to 10), conductor 419, bank terminal 336 and brush 334 of selector switch 350, the contact of cam 310 (8), conductor 313, bank terminal 260 and brush 263 of selector 250, the upper right hand and lower contacts of cam 218, conductors 264 and 243, the inner right hand armature and front contact of relay 235, wiper 244, conductor 653, the right hand contact of cam 611 (13 to 18), the upper contacts of cam 717 (2), the left hand winding of relay 734, conductor 735, the windings of stepping relay 719, the armature and back contact of relay 720, the left hand contacts of cam 714 (1 to 16), the upper contact of cam 615 (13 to 18) and thence over the circuit previously traced to ground at the lower contact of cam 405 (1 to 8). Upon the extension of the connection to the final selector switch, relay 421 of the incoming selector switch, which was energized in position 7 of sequence switch 400, is maintained energized in position 8 of sequence switch 400 over a circuit extending from grounded battery through the right hand winding of relay 421, conductor 422, the right hand contacts of sequence switch cam 402, conductor 428, the right hand armature and front contact of relay 421, conductor 429, the lower right hand contact of sequence switch cam 414 (7 to 8), brush 448, terminal 449, trunk conductor 519, the upper left hand and lower right hand contacts of sequence switch cam 505, resistance 520 and thence to ground through the lower left hand contact of sequence switch cam 506 (1 to 8 $\frac{1}{2}$). Busy ground potential is placed on the multiples of test terminal 451 of the selected trunk over test brush 442, and the lower right hand and upper left hand contacts of sequence switch cam 412.

Final brush or hundreds selection.

Upon the extension of the fundamental circuit to the final selector switch 550, with the sender sequence switch 700 in position 2, relay 518 of the final selector and stepping relay 719 of the office sender both energize. Relay 518 closes a circuit for relay 521, which may be traced from grounded battery through the left hand winding of this relay, conductor 522, the upper left hand contact of sequence switch cam 507 (1), conductor 523, the left hand armature and front contact of relay 518 and thence to ground through the upper contact of sequence switch cam 508 (1 to 11). Relay 521 ener-

gizes in this circuit and at its left hand armature and front contact closes a locking circuit for itself extending from grounded battery through its left hand winding 5 through the armature and back contact of test relay 524, the left hand armature and front contact of relay 521, sleeve conductor 525, bank terminal 451 and brush 442 of the incoming selector switch, and thence to 10 ground at sequence switch cam 412. Relay 521 upon energizing, closes a circuit for driving sequence switch 500 out of its normal position 1 into position 2, which circuit may be traced from grounded battery 15 through the winding of magnet 500, through the lower contacts of sequence switch cam 509 and to ground at the right hand armature and front contact of relay 521. When sequence switch 500 moves out of position 1 20 the initial energizing circuit of relay 518 is opened at the lower left hand contact of sequence switch cam 503 but relay 518 remains energized over the fundamental circuit by reason of a locking circuit extending 25 from grounded battery, through the upper left hand contact of sequence switch cam 504, the right hand winding of relay 518, the lower right hand contact of sequence switch cam 510 (15 to 10), the right hand armature and front contact of relay 518, the lower right hand contact of sequence switch cam 503 (1 to 6) and thence through the left hand contact of sequence switch cam 502 and over the fundamental circuit as previously traced. Relay 518 upon energizing, 30 with sequence switch 500 in position 2, closes a circuit for the high speed up drive magnet 526, which may be traced from grounded battery through the upper right hand contact of sequence switch cam 511 (2), conductor 523, the left hand armature and front contact of relay 518 and thence to ground at the upper left hand contact of sequence switch cam 508. Magnet 526, upon energizing, 35 presses the depending portion of the switch shaft 527 against the constantly rotating high speed roller 528, thereby causing the switch shaft to be moved upwardly at a high speed in its brush selection movement. During the upward movement of the switch shaft, an intermittent ground is 40 connected to the fundamental circuit for intermittently shunting down relay 719 of the office sender, over a circuit traced from a junction point between the windings of relay 719 and relay 518 (sequence switch cam 502), which may be traced through the upper right hand contact of sequence switch cam 502 (14 to 2), conductor 529, brush selection segment 530 of the commutator 531, brush 532, conductor 533 and thence to ground through the upper left hand contact of sequence switch cam 506 (13 to 11). 45

On the initial closure of the fundamental

circuit through the winding of relay 518 65 and the windings of sender stepping relay 719, with sequence switch 700 in position 2, a circuit is closed for the No. 4 counting relay 764, extending from grounded battery 70 through the winding of relay 764, the armature and back contact of upper No. 4 counting relay 765, lead 766, lead 970 Fig. 9, contact 911 and wiper 912 of the hundreds register H which was set in position 5 by the calling subscriber, conductor 913, the lower 75 right hand contact of sequence switch cam 715 (2), conductor 771, contact 755 (4) of class switch 750, conductor 772, the left hand contact of translator control sequence switch cam 613 (13 to 18), conductor 741 80 and thence to ground through the contacts of sequence switch cams 702 and 703 and the armature and contact of stepping relay 719. Counting relay 764 energizes in this circuit closing a locking circuit for itself 85 through the winding of counting relay 765 as previously described, and in response to successive energizations and de-energizations of stepping relay 719, the counting relays 768, 737, 743 and 730 energize in succession and upon the last de-energization of relay 719, relay 731 energizes, closing a circuit as previously traced through the upper left hand contact of sequence switch cam 704 (2) for driving sequence switch 700 out 90 of position 2 and into position 4. Upon leaving position 2 the locking circuit of the energized counting relays is opened at sequence switch cam 703 as previously described. 95

At the time upper No. 0 counting relay 731 energizes, relay 720 also energizes opening at its armature and back contact the fundamental circuit extending through the winding of relay 518 of the final selector switch. Relay 518 thereupon de-energizes and at its left hand armature and front contact opens the energizing circuit of the up drive magnet 526 to arrest the upward movement of the switch shaft, and at its left hand armature and back contact closes a circuit for driving sequence switch 500 out 105 of position 2 and into position 3, this circuit extending from grounded battery through the winding of sequence switch 500, the upper right hand contact of sequence switch cam 512 (2), the left hand armature and back contact of relay 518 and thence to ground at the upper contact of sequence switch cam 508. The fifth set of 110 brushes has now been positioned with relation to the tripping fingers on the tripping spindle 584 so that upon a subsequent upward movement of the switch shaft this set of brushes will be tripped for engagement 115 with the bank of 100 terminals with which this brush set is associated. To cause the tripping of this set of brushes, the trip mag- 120

net 535 is energized over a circuit extending from grounded battery, through the trip magnet 535 and thence to ground at the lower right hand contact of sequence switch 506 (3 to 5) as soon as sequence switch 500 reaches position 3.

Final group or tens selection.

When sequence switch 500 reaches position 3 the energizing circuit of relay 518 is again established over the fundamental circuit as previously described and relay 518 and stepping relay 719 of the office sender energize in series. Relay 518, upon energizing, again closes the previously traced circuit for driving sequence switch 500 out of position 3 and into position 4. With sequence switch 500 in position 4 the previously traced circuit for the up drive magnet 526 is again established at the left hand armature and front contact of relay 518. Relay 518 also establishes the previously traced locking circuit for itself extending through its right hand armature and front contact for maintaining itself energized over the fundamental circuit after sequence switch 500 leaves position 3 and opens the initial energizing circuit at the lower left hand contact of sequence switch cam 503. Upon the energization of the high speed up drive magnet 526, the switch shaft 527 is driven upwardly in its group hunting movement and during the initial portion of this movement the fifth set of brushes is tripped by the fingers of the spindle 534, and during the remainder of the group selecting movement the tripped set of brushes travel upwardly in contact with the terminals of the bank with which the brush set is associated. During this group selection movement of the switch shaft an intermittent ground is connected to the fundamental circuit through the junction point (sequence switch cam 502), over a circuit extending through the upper right hand contact of sequence switch cam 503 (3 to 4), conductor 536, group selection segment 537, brush 538, conductor 533, and thence to ground through the upper left hand contact of sequence switch cam 506.

Stepping relay 719 of the office sender energizing over the fundamental circuit previously traced through relay 518 at the final selector, with sequence switch 700 in position 4, closes a circuit for the No. 3 counting relay 768 over a circuit extending from grounded battery through the winding of counting relay 768, the armature and back contact of upper No. 3 counting relay 773, lead 774, lead 774 Fig. 9, terminal 914 and wiper 915 of the tens register T which was set into position 3 by the calling subscriber dialing digit 3, thence over conductor 916, through the upper right hand contact of

sequence switch cam 715 (4), and over the circuit previously traced to ground at the contact of sequence switch cam 703. In the manner previously described, the counting relays energize in succession until the upper No. 0 counting relay 731 energizes in parallel with relay 720.

Relay 731, upon energizing, closes the circuit previously traced, for driving sequence switch 700 out of position 4 and into position 6. Sequence switch 700, upon leaving position 4, opens the locking circuits of the energized counting relays and these counting relays restore to normal position. Relay 720, upon energizing, opens the fundamental circuit thereby causing the de-energization of relay 518 at the final selector.

Relay 518, upon de-energizing, opens the circuit of the up drive magnet 526 and closes the circuit previously traced for driving sequence switch 500 out of position 4 and into position 5. In position 5 the fundamental circuit extending through the windings of stepping relay 719 and the right hand winding of relay 518 is again established and relay 518, upon energizing, closes the previously traced locking circuit for itself, and closes the circuit for driving sequence switch 500 out of position 5 and into position 6. Upon reaching position 6 a circuit is established for the low speed up-drive magnet 539, which circuit may be traced from grounded battery through the winding of magnet 539, the lower left hand contact of sequence switch cam 507 (6), conductor 523, the left hand armature and front contact of relay 518 and thence to ground at the upper left hand contact of sequence switch cam 508. The low speed up drive magnet 539 upon energizing, presses the depending portion of the switch shaft 527 against the constantly rotating low speed roller 540 thereby causing the upward movement of the switch in its units selection movement. During this upward movement of the switch shaft an intermittent ground is connected to the junction point (cam 502) in the fundamental circuit between the windings of stepping relay 719 and the windings of relay 518, over a circuit which may be traced from the upper right hand contact of sequence switch cam 502 (5 to 6), conductor 529, units selection portion of commutator segment 530, brush 532, conductor 533, and thence to ground through the upper left hand contact of sequence switch cam 506.

The stepping relay 719 of the office sender energizing in the fundamental circuit, with the sender sequence switch 700 in position 6, a circuit is closed for the No. 2 counting relay 737, which circuit may be traced from grounded battery through the winding of relay 737, the armature and back contact of upper No. 2 counting relay 738, lead 739,

lead 917 Fig. 9, terminal 918 and brush 919 of the units register which was set in position 2 when the calling subscriber dialed the No. 2 units digit, conductor 920, the upper left hand contact of sequence switch cam 715 and thence over the circuit previously traced to ground at the contact of sequence switch cam 703. In response to the successive energizations and de-energizations of relay 719, counting relays 743 and 730 energize in succession and, when the upper counting relay 731 energizes in parallel with relay 720, a circuit is closed for driving sequence switch 700 out of position 6 and into position 8. Relay 720, upon energizing, opens the fundamental circuit thereby causing the de-energization of line relay 518 of the final selector switch which in turn opens the circuit of the up drive magnet 539 and closes the previously traced circuit for driving sequence switch 500 out of position 6 and into position 9.

Testing the called line.

25 The brushes of the final selector switch 550 have now been positioned upon the terminals of the desired line and sequence switch 500 upon reaching position 9 closes a circuit for re-energizing relay 518, which 30 may be traced from grounded battery through the left hand contact of sequence switch cam 504 (1 to 10), the right hand winding of relay 518, lower right hand and upper left hand contacts of sequence switch cam 510 and thence to ground at the right hand armature and front contact of relay 521. Relay 518, upon energizing, closes a locking circuit for itself extending from grounded battery through its right hand winding, the lower right hand contact of sequence switch cam 510, the right hand armature and front contact of relay 518 and thence to ground through the upper contacts of sequence switch cam 513. This locking circuit will be maintained through position 40 of sequence switch 500. Relay 518 upon energizing, also closes a circuit as previously traced for driving sequence switch 500 out of position 9 and the sequence switch 50 will continue to rotate under the influence of its master cam 501 through intermediate positions into position 12. Upon reaching position 10 a new holding circuit is established for relay 518 extending from grounded battery through the left hand winding of relay 518, the lower right hand contact of sequence switch cam 515, the left hand armature and front contact of relay 518 and thence to ground at the upper left hand contact of sequence switch cam 508. Upon reaching position 11 sequence switch 500 establishes a new holding circuit for relay 518 extending from ground through the winding of test relay 524, conductor 541, the upper left hand contact of sequence switch cam 502, the lower

left hand contact of sequence switch cam 508, the right hand winding of relay 518, the upper right hand contact of sequence switch cam 510, the right hand armature and front contact of relay 518, the right hand contacts of sequence switch cam 513, test brush 542 and thence to battery on the test terminal of the called line if the called line is busy. If the called line is busy as a calling line this battery potential will be connected to the test terminal 543, as previously described in connection with the trunk hunting switch 100 through an off normal contact of the trunk hunting switch, and if the called line is busy as a called line, battery potential will be supplied to the terminal 543 from grounded battery through the upper right hand contact of a sequence switch cam 504 of the final selector switch which is in engagement with the terminals of the called line, the lower contacts of a cam corresponding to cam 513 and the test brush of such final selector switch.

Called line a direct line and idle.

It will be assumed that the called line is found to be idle and ground potential is encountered on the test terminal 543. This ground potential is supplied through a wiper of the called subscriber's trunk finding switch 95 corresponding to wiper 110, shown in Fig. 1, and the windings of the called subscriber's cut off relay. Therefore, when the test circuit through test brush 542 is established to this idle line, the circuit previously traced through the right hand winding of relay 518 and the winding of relay 524 will extend from ground to ground and relay 518 will therefore become de-energized when sequence switch 500 leaves position 11, and relay 524 will not energize. When, therefore, relay 518 de-energizes it closes a circuit for driving sequence switch 500 out of position 12 and into position 13, this circuit extending from grounded battery magnet winding of switch 500 through the upper right hand contact of sequence switch cam 512, the left hand armature and back contact of relay 518, the lower left hand contact of sequence switch cam 508 and thence to ground at the right hand armature and front contact of relay 521. Upon reaching position 13, a circuit is established over the lower contacts of sequence switch cam 509 and the right hand armature and front contact of relay 521 for driving sequence switch 500 out of position 13 and into position 14, and in position 14 a circuit is established as previously traced through the winding of sequence switch magnet 500, the right hand armature and back contact of relay 518 and thence to ground at the upper left hand contact of sequence switch cam 508 for driving the sequence switch into the talking position 15, in which position the trunk conductors 517

and 519 are connected respectively to the brushes 552 and 553 over the lower contacts of sequence switch cam 502 and the upper contacts of sequence switch cam 505.

5 *Talking election.*

Following the test of the called line, assuming that the called line is found to be idle, the sequence switch 500 moves into the 10 talking position 15 and upon leaving position 8₁ opens the circuit previously traced extending over ring conductor 519 and through the winding of relay 421 of the incoming selector thereby causing the de-energization of this relay. Relay 421, upon de-energizing closes a circuit for driving sequence switch 400 out of position 8 and into position 9. This circuit may be traced from grounded battery through the winding of magnet 400, the upper left hand contact of sequence switch cam 406 (8), and thence to ground at the inner left hand armature and back contact of relay 421. With sequence switch 400 in position 9, relay 421 is again connected into the fundamental circuit extending through the windings of sender stepping relay 719 and the winding of over flow relay 734 at the office sender, but at this time the winding of relay 421 is connected to the ring conductor of the fundamental circuit rather than to the tip conductor as heretofore described so that current flowing in the fundamental circuit now flows in a direction reverse to the direction in which it originally flowed. The connection of relay 421 to the ring conductor 420 of the fundamental circuit at the incoming selector switch may be traced from grounded battery through the right hand winding of relay 421, the lower contacts of sequence switch cam 415 (9), resistance 425, and the lower contact of sequence switch cam 404 (1 to 10). The tip conductor 419 of the fundamental circuit is connected to ground at the incoming selector over a circuit which may be traced from conductor 419 through the upper contact of sequence switch cam 403 (1 to 10), resistance 424, the left hand contacts of sequence switch cam 508 and thence to ground through the upper contacts of sequence switch cam 412. During the time the final selector switch was functioning to test the called line and the incoming selector switch was functioning to reverse the direction of the current flow over the fundamental circuit, the sequence switch 700 of the sender moved from position 8 into position 14, since at this time counting relay 731 is locked up to maintain the driving circuit of sequence switch magnet 700 until sequence switch 700 reaches position 14. The locking circuit of relay 731 may be traced from grounded battery through the windings of relays 730 and 731, the armature and front contact of relay

730, conductor 742, the upper left and lower right hand contacts of sequence switch cam 712 (6 to 12), contacts of class switch cam 756 (4), conductor 775 and thence to ground through the upper right hand contact of sequence switch cam 619.

When sequence switch 700 reaches position 14, the locking circuit for relay 731 is opened and a circuit is established for relay 749 which may be traced from grounded battery through the winding of relay 749 and thence to ground through the contacts of sequence switch cam 710 (14). Relay 749, upon energizing, closes a circuit for driving translator control sequence switch 600 out of position 13 and into position 14, which circuit may be traced from grounded battery through the magnet winding 600, the lower contact of sequence switch cam 616 (13), the upper left hand contact of sequence switch cam 616, conductor 764, the armature and contact of relay 749 and thence to ground through the lower contacts of class switch cam 754 (4). A circuit is also closed at this time for driving sender sequence switch 700 into position 16, this circuit extending from grounded battery through the magnet winding 700, conductor 763, the upper contacts of sequence switch cam 616, and thence to ground at class switch cam 754 over the circuit previously traced.

With the sequence switch 400 of the incoming selector in position 9 and the sequence switch 700 of the office sender in position 16, the line relay 421 of the incoming selector, the stepping relay 719 of the office sender and the over flow relay 734 become energized. Current now flowing through the winding of relay 734 is in such a direction as to operate y energize it and cause it to close a circuit for relay 776 which may be traced from grounded battery through the left hand winding of this relay, the contact of sequence switch cam 716 (16) and thence to ground through the armature and front contact of relay 734. Relay 776, upon energizing, closes a locking circuit for itself extending from grounded battery, through its right hand winding, its right hand armature and front contact and thence to ground at the upper left hand contact of translator control sequence switch cam 606.

With the sequence switch 700 in position 16 a circuit is closed for the No. 0 counting relay 730, which may be traced from battery through the winding of relay 730, the contact of cam 709 (11 to 18), lead 745, the lower left hand contact of cam 715 (16), conductor 771, the contact of class switch cam 755 (4), conductor 772, the left hand contact of cam 613 (13 to 18), conductor 741, the lower left hand and upper right hand contacts of cam 702 (16), the armature and contact of relay 719 and thence to ground

at the lower left hand contact of cam 703. Relay 730 locks up through the winding of relay 731. At the incoming selector 450, relay 421 energizes over the fundamental circuit and at its right hand armature and front contact establishes a circuit for relay 451 which may be traced from battery through the winding of relay 451, the right hand contact of cam 416 (9 to 10), the right hand armature and front contact of relay 421 and to ground through the upper contacts of cam 412. Relay 451, upon energizing, closes a circuit extending from battery through the magnet winding of sequence switch 400, the armature and front contact of relay 451 and to ground at the left hand contacts of cam 12. As soon as sequence switch 400 reaches position 10, the fundamental circuit is opened and relays 719, 734 and 421 de-energize, relay 421 opening the circuit of relay 451 which in turn opens the circuit of sequence switch magnet 400 to arrest the sequence switch in position 10.

Upon the opening of the fundamental circuit and the de-energization of relay 719, the upper No. 0 counting relay 731 energizes in series with relay 730. With relay 776 now energized a circuit is now established for advancing sequence switch 700 into position 17 which may be traced from battery through the magnet winding of switch 700, the upper left hand contact of cam 704 (16), the left hand armature contacts of relay 776 and to ground at relay 731. A circuit is also established at this time for energizing advance relays 656 and 658, which circuit may be traced from battery through the windings of these relays in parallel, conductor 662, the left hand armature and outer front contact of relay 776 to ground at relay 731. Relay 658, upon energizing, closes a locking circuit for itself and for relay 656 extending through its right hand armature contact and to ground at the upper contact of cam 606 (13 to 18).

With sequence switch 700 in position 17, a local circuit for relay 719 is established from battery through the winding of relay 749, the right hand contacts of cam 717 (17), the left hand winding of relay 734, the windings of relay 719, the armature and contact of relay 720, the left hand contacts of cam 706 to ground through resistance element 722. Relay 719 upon energizing advances sequence switch 700 into position 18 over a circuit extending through the magnet winding of switch 700, the lower right hand and upper left hand contacts of cam 702 (17), the armature and front contact of relay 719 and to ground at the upper right hand contact of cam 703. Switch 700 in advancing out of position 17 opens the circuit of relay 719 and in position 18 prepares the circuits of the sender for controlling the

talking selection movement of the sequence 65 switch of the district selector.

The energization of advance relay 656 opens the circuit previously traced through the winding of relay 261 at the district selector switch, through the left hand armature and back contact of advance relay 656 and to ground at sequence switch cam 614, whereupon relay 261 at the district selector de-energizes, opening the circuit of relay 228 which thereupon establishes the previously traced circuit for driving sequence switch 200 out of position 10 and into position 11. The energization of relay 656 also opens the circuit of sender control relay 663 which has, during the setting up of the connection, been held energized over a circuit extending from battery through its right hand winding, the right hand armature and back contact of relay 656 and to ground at sequence switch cam 614, and this relay, de-energizing, opens the circuit of relay 650 which establishes a new energizing circuit for relay 228 of the district selector switch which may be traced from battery through the left hand winding of relay 228, the upper right hand and lower left hand contacts of sequence switch cam 210 (11), conductor 243, the inner right hand armature and front contact of relay 235, wiper 244, conductor 653, the right hand contact of sequence switch cam 611, the upper contacts of sequence switch cam 717, the left hand winding of relay 734, conductor 735, windings of relay 719, the armature and back contact of relay 720, conductor 721, the outer right hand armature and back contact of relay 650, conductor 651 and thence to ground through resistance 722. Relays 228 and 719 energize in this circuit and relay 228 closes a circuit as previously traced for driving sequence switch 200 out of position 11 and into position 15 unless the circuit is interrupted at the armature contacts of relay 228 prior to the sequence switch reaching position 15. After sequence switch 200 leaves position 11 relay 235 is maintained energized to hold the circuit of relay 228 closed over a circuit which may be traced from grounded battery through the winding of magnet 233, the winding of relay 235, the lower contact of sequence switch cam 216 (11 to 14), the outer right hand armature and front contact of relay 235, the upper contact of sequence switch cam 217 (11 to 16), the outer right hand armature and front contact of relay 228 and thence to ground through the lower contacts of sequence switch cam 215.

During the rotation of sequence switch 200 from position 11 into position 15, an intermittent ground is connected to the circuit extending through the windings of relays 719 and 228, between the windings of

these two relays in such a manner as to hold the relay 228 energized and to shunt down relay 719. This intermittent ground connection extends from the left hand winding 6 of relay 228 through the left hand armature and front contact of this relay and thence to ground through the upper left hand and lower right hand contacts of sequence switch cam 215, and is closed in positions 11 $\frac{1}{2}$, 12 $\frac{1}{2}$ 10 and 13 $\frac{1}{2}$.

With the sender sequence switch 700 in position 18 and the sender relay 719 energized, a circuit is established for the No. 0 counting relay 730, assuming that the 15 talking selection relays have been so set by the code letters dialed by the calling subscriber as to adjust the connections of the repeating coil 267 at the district selector for efficient talking over a non-loaded inter- 20 office trunk. This circuit may be traced from grounded battery through the winding of counting relay 730, the contact of sequence switch cam 709, lead 745 Fig. 7, lead 1031 Fig. 10, the inner left hand armature and front contact of talking selection register relay 1017, the right hand armature and back contact of talking selection register relay 1032, conductor 1033, the lower left hand and upper right hand contacts of se- 25 quence switch cam 718 (18) and thence to ground through the armature and contacts of stepping relay 719 and the contacts of sequence switch cam 703 as previously traced. Relay 730 energizes in this circuit and closes 30 a locking circuit for itself extending through its winding, the winding of the upper No. 0 counting relay 731, the armature and front contact of relay 730, conductor 727, conductor 742 and thence to ground through 35 the upper contact of sequence switch cam 703. Upon the first de-energization of relay 719 when the sequence switch 200 of the district selector is passing through position 11 $\frac{1}{2}$, counting relay 731 energizes in parallel with relay 720. Relay 720, upon energizing, opens the circuit previously traced 40 extending through the windings of relays 719 and 228, and relay 228, upon de-energizing, opens the previously traced circuit ex- 45 tending through the winding of the magnet of sequence switch 200 for arresting switch 200 in position 12.

Relay 731, upon energizing, closes a circuit for driving the translator control 50 sequence switch 600 out of position 14 and into position 15, this circuit extending from grounded battery through the magnet winding of sequence switch 600 the lower right hand contact of sequence switch spring 607 55 (14), conductor 661, the right hand contacts of sequence switch spring cam 714, (18), and thence to ground at the armature and front contact of relay 731. Translator control se- 60 quence switch 600, upon reaching position 15, 65 closes a circuit for advancing the sender

sequence switch 700 out of position 18 and into normal position 1. This circuit may be traced from grounded battery through the winding of sequence switch magnet 700, the lower left hand contact of sequence switch 70 cam 704 (18) and thence to ground through the lower right hand contact of sequence switch cam 606 (15 to 1). Sequence switch 700, upon moving out of position 18, opens the locking circuit of relays 730 and 731 75 and the counting relays are then restored to normal position.

Restoration of the office sender.

As soon as the district selector sequence switch 200 leaves position 10 $\frac{1}{2}$ in response to the energization of advance relays 656 and 658, the impulse leads 240 and 241 which up to this time have connected the substation of the calling subscriber with the stepping relay 800 of the office register circuit, are disconnected from the district selector trunk conductors 116 and 117 at the contacts of sequence switch cams 212 and 213, and these trunk conductors are connected through the right hand contacts of these cams to the left hand windings of repeating coil 267. Upon the opening of the circuit over impulse leads 240 and 241, stepping relay 800 de-energizes opening the circuit of the slow releasing relay 802. Relay 802, upon de-energizing, closes a circuit extending from ground through the normal contacts of its right hand armature, over wiper 842, the contacts of the restoring bank 843, the armature and back contact and winding of stepping magnet 817 of the register steering switch RS and thence to grounded battery through the winding of relay 816. Stepping magnet 817 thereupon causes the restoration 90 of the steering switch into its normal position. At the time the restoration of the register steering switch RS was initiated, the wipers of this switch were standing on the tenth set of terminals by virtue of a circuit 95 which was established as soon as the calling subscriber dialed the last digit through the stepping magnet 817, wiper 844, the No. 7 terminal 845 with which the wiper 844 is 100 in engagement, conductor 846, the contacts of class switch cam 757, (13 to 11), contacts of translator control sequence switch cam 620 (9 to 13), and to ground through the No. 16 contact 664 and wiper 630 of the time measure switch, and also by virtue of simi- 105 lar circuits established through the wiper 630 of the time measure switch, the contacts of class switch cam 758, conductors 778 and 779, and the No. 8 and No. 9 contacts 110 845 and 846 of the register steering switch. 115

Upon the de-energization of relay 228 of the district selector switch upon the completion of the talking selection movement of sequence switch 200, the circuit of relay 235 is opened and this relay at its inner left 120 125 130

hand armature and front contact opens the holding circuit of relay 625. Relay 625 upon de-energizing, closes a restoring circuit for the time measure switch TM which may be traced from grounded battery through stepping magnet 626 of this switch, the armature and contacts of this magnet, wiper 665, the contacts of the bank with which this wiper is associated and thence to ground at the armature and back contact of relay 625. Under the influence of magnet 626, the time measure switch is restored to normal position. When the time measure switch reaches normal position, a circuit is closed for driving the translator sequence switch 600 out of position 15 and into position 18. This circuit may be traced from grounded battery through the winding of magnet 600, the contact of sequence switch cam 621 (2 to 17) and thence to ground at the normal contact and wiper 639 of the time measure switch. If the translator switch TS has reached normal position at this time, a circuit is completed for continuing the movement of sequence switch 600 out of position 18 and into normal position. This circuit may be traced from grounded battery through the winding of magnet 600, the lower contact of sequence switch cam 607 (18), conductor 666, and thence to ground at the armature and back contact of relay 1169.

In the movement of the translator control sequence switch 600 through positions 12 to 18, a circuit was established for restoring the code registers to normal position. The circuit for restoring register A extends from grounded battery through the left hand armature and back contact of relay 808, conductor 809, the winding of relay 810, conductor 811, the winding of stepping magnet 807 of register A, the armature and contact of stepping magnet 807, the contacts of restoring bank 847 and wiper 848 of register A, conductor 849, and thence to ground at the upper contact of translator control sequence switch cam 622. When register A reaches normal position a similar circuit is established for stepping magnet 819 of register B extending through the winding of this magnet, the armature and contact of the magnet, contacts of restoring bank 850, wiper 851, conductor 852, the normal contact of restoring bank 847 of register A, wiper 848 in engagement therewith, conductor 849 and thence to ground through sequence switch cam 622. Register B, upon reaching normal position transfers the restoring circuit extending from sequence switch contact 622, from the winding of stepping magnet 819, to the winding of stepping magnet 812, through the restoring bank 853, and wiper 854 of register C.

When the translator control sequence switch 600 passes from position 14 to po-

sition 18, a circuit is closed for restoring the thousands, hundreds, tens and units registers in succession. The circuit for restoring the thousands register TH may be traced from grounded battery over the circuit previously traced through the windings of relay 810 and stepping magnet 921 of the thousands register, thence through the armature and contacts of magnet 921 the contacts of restoring bank 922, wiper 923, conductor 924 and thence to ground at the lower right hand contact of sequence switch cam 622. When the thousands register reaches normal position, the restoring conductor 924 becomes connected through wiper 923 of the thousands register and the normal contact upon which it is then resting to conductor 925, wiper 926, the contacts of the restoring bank 929 upon which the wiper 926 is resting and thence through the armature, contacts and magnet winding 928 of the hundreds register. In a similar manner the hundreds register, upon reaching normal position, establishes a restoring circuit extending through the winding of the tens register 929, and the tens register, upon reaching normal position, extends the restoring circuit through the stepping magnet 930 of the units register.

As soon as the translator control sequence switch leaves position 11, battery is removed at sequence switch cam 610 from the circuit extending through the winding of skip office register relay 1012 to unlock this relay if it is at the time energized. Upon leaving position 13, battery is disconnected from conductor 647 for unlocking the energized district brush, office brush, district group, office group, register relays, which have been locked up, and upon leaving position 14, battery is disconnected from conductor 646 for unlocking the talking selection relay 1017 which was energized and locked up for controlling the talking selection. Upon leaving position 18 the translator control sequence switch opens the locking circuit for relay 776 of the office sender, restoring this relay to its normal condition. The circuits of the office sender are now restored to normal condition for controlling subsequent calls.

Ringing the called substation.

During the setting of the sequence switch 200 of the district selector switch 250 into its talking position, sequence switch 400 of the incoming selector has been standing in position 10. As soon as the sequence switch 200 of the district selector has advanced to the selected talking position, a circuit is established for relay 421 extending through the right hand winding of this relay, through the upper contacts of sequence switch cam 402, conductor 423, resistance 424, the upper contact of sequence switch

403 (1 to 10), trunk conductor 419, bank terminal 336 and brush 334 of the office selector switch, the contact of sequence switch cam 310 (8), conductor 313, bank terminal 260 and brush 263 of the district selector switch, the upper contacts of sequence switch cam 218, the uppermost right hand winding of repeating coil 267, the upper contacts of sequence switch cam 220, the 10 windings of polarized supervisory relay 268, the lower contact of sequence switch cam 221, the lowermost right hand winding of repeating coil 267, the upper contacts of sequence switch cam 219, brush 264 and terminal 259 of the district selector switch, trunk conductor 314, contact of sequence switch cam 311 (8), brush 335 and terminal 337 of the office selector switch, trunk conductor 420, the lower contact of 15 sequence switch cam 404 (1 to 10), resistance 425, conductor 426, and thence through the lower contact of sequence switch spring 405 (10) to ground. Relay 421 upon energizing locks to ground on sleeve conductor, 20 2464, over a circuit extending from grounded battery through its left hand winding, the armature and back contact of relay 455, the upper left hand contact of cam 409, the outer left hand armature and front contact of 25 relay 421 conductor 427 and thence to conductor 465 through the upper contact of cam 407. When relay 421 re-energizes, the 30 circuit of relay 451 is again established and the sequence switch is driven to position 11. 25 With the sequence switch 400 in position 11, the circuit of relay 451 is again established over the upper contact 452 of interrupter cam 453 and the upper left hand contact 35 of sequence switch cam 416 (11). A circuit is also established in position 11 of sequence switch 400 for applying a steady flow of ringing current to the line of the 40 called subscriber. The circuit over which ringing current is transmitted may be traced from the source of ringing current 454 through the lower left hand and upper right hand contacts of sequence switch cam 417 (11 to 12), through the winding of ringing cut off relay 455, the lower contacts of sequence switch cam 402 (11 to 13), conductor 428, the right hand armature and front contact of relay 421, conductor 429, the lower right hand contact of sequence switch cam 414, brush 448 and terminal 449 of the incoming selector switch, trunk conductor 519, the upper contacts of sequence switch cam 505, brush 553 and terminal 557 of the final selector switch, and thence through the called subscriber's bell 558 and back over terminal 559 and brush 552 of the final selector switch, the lower contacts of sequence switch cam 502, trunk conductor 517, bank terminal 447 and brush 446 of the incoming selector switch and thence to ground at the 55 upper right hand contact of sequence switch

cam 413. As soon as relay 451 energizes in position 11 of sequence switch 400, the circuit previously traced through the armature and front contact of relay 451 is established for driving sequence switch 400 out of position 11 and into position 12. In position 12 relay 451 is energized as soon as a circuit therefor is established over the lower left hand contact of sequence switch cam 416 (12) and the lower contact 452 of the interrupter cam 453, and upon its energization drives sequence switch 400 out of position 12 and into position 13. In position 13 the source of ringing current 454 is connected over the circuit previously traced through the interrupter 456 and the right hand contacts of the sequence switch cam 417, and the called subscriber's bell 558 is operated intermittently until the called subscriber responds. During the application of ringing current to the called subscriber's line, a ringing tone is transmitted back to the calling subscriber's substation through the lower left hand contact of sequence switch cam 413, and through the lower left hand contact of sequence switch cam 414, condenser 457 and the lower right hand and upper left hand contacts of sequence switch cam 418. 95

Response of the called subscriber.

In response to the ringing of bell 558 the called subscriber removes his receiver from its switch hook, thereby cutting the bell 558 from the line loop and connecting a direct current bridge across the line loop at the substation. Current flowing over the subscriber's line loop from the source 454 now causes the operation of ringing cut off relay 455 which upon energizing, opens at 100 its armature and back contact the locking circuit extending through the left hand winding of relay 421. Relay 421 thereupon de-energizes and opens the circuit over which ringing current was applied to the called line, at its right hand armature and front contact, and at its inner left hand armature and back contact closes a circuit extending through the upper left hand contact of sequence switch cam 406 for driving sequence switch 400 out of position 13 and into position 16. When sequence switch 400 passes through position 14, relay 421 again energizes over a circuit extending from grounded battery through its left hand winding and the right hand contacts of sequence switch cam 411, and closes a locking circuit for itself extending through its left hand winding, the armature and back contact of ringing cut off relay 455, the upper left hand contact of sequence switch cam 409, conductor 431, the outer left hand armature and front contact of relay 421, conductor 427, the upper contact of sequence switch cam 407 and thence over the sleeve 115

120

125

130

conductor of the trunk and to ground connected as previously described to this sleeve conductor.

As soon as sequence switch 400 reaches position 14, a direct current path is established through the right hand windings of repeating coil 458 and thence over the called subscriber's line loop for supplying the called subscriber with talking current. This path may be traced from the non-grounded pole of battery through the lower right hand winding of repeating coil 458, the winding of supervisory relay 459, the upper left hand contact of sequence switch cam 414, brush 448 and bank terminal 449 of the incoming selector switch, trunk conductor 519, the upper contacts of sequence switch cam 505, brush 553, and bank terminal 557 of the final selector switch, and thence over the called subscriber's line and through his substation apparatus and returning over bank terminal 559 and brush 552 of the final selector switch, the lower contacts of sequence switch cam 502, trunk conductor 517, bank terminal 447 and brush 446 of the incoming selector switch, the lower left hand contact of sequence switch cam 413 and thence to the grounded pole of battery through the upper right hand winding of repeating coil 458. Supervisory relay 459 energizes in this circuit and connects the terminals of the central station battery between the left hand windings of the repeating coil 458 in such a manner as to cause current to flow over the trunk line extending between the incoming selector switch and district selector switch in such a direction as to energize polarized supervisory relay 268 at the district selector switch to close its alternate contact. This circuit may be traced from the non-grounded pole of central office battery over conductor 460, the upper left hand contact of sequence switch cam 405 (11 to 16), conductor 426, resistance 425, the upper contacts of sequence switch cam 415 (11 to 16), the lower left hand winding of repeating coil 458, the upper contact of sequence switch cam 404 (11 to 16), trunk conductor 420, bank terminal 337 and brush 335 of the office selector switch, the contact of sequence switch cam 311 (8), trunk conductor 314, bank terminal 259 and brush 264 of the district selector switch, the upper contacts of sequence switch cam 219, the lowermost right hand winding of repeating coil 267, the lower contact of sequence switch cam 221, the windings of relay 268, the upper contacts of sequence switch cam 220, the uppermost right hand winding of repeating coil 267, the upper contacts of sequence switch cam 218, brush 263 and bank terminal 260 of the district selector switch, conductor 313, contact of sequence switch 310, (8), brush 334 and

bank terminal 336 of the office selector switch, trunk conductor 419, the lower contact of sequence switch 403, the upper left hand winding of repeating coil 458, resistance 424 and thence through the armature 70 and front contact of relay 459 to ground.

As soon as sequence switch 200 of the district selector arrived in position 10 $\frac{1}{4}$ following the advance of the district selector and the disconnection of dialing leads 240 and 241, a direct current path was established from central station battery and through the left hand windings of repeating coil 267 over the calling subscriber's line loop for energizing the calling supervisory relay 269. 80 This circuit may be traced from the non-grounded pole of battery through the lower left hand winding of repeating coil 267, the winding of supervisory relay 269, the upper right hand contact of sequence switch cam 213, trunk conductor 116, wiper 111 of the subscriber's trunk hunting switch, the innermost lower armature and front contact of relay 102, line conductor 103, the substation circuit of the calling subscriber's line, line conductor 104, the upper armature and front contact of relay 102, wiper 113, the trunk conductor 117, the lower right hand contact of sequence switch cam 212 and thence to the grounded pole of the central station battery, through the upper left hand winding of repeating coil 267. Relay 269, upon energizing, closes a circuit for holding relay 227 energized until the calling subscriber releases the connection. This holding circuit for relay 227 may be traced from grounded battery through the winding of relay 227, the armature and front contact of relay 269, and thence to ground through the right hand armature and front contact of relay 227. The calling and called subscribers are now connected over a talking circuit with each other, the calling subscriber receiving talking current over the circuit previously traced through the left hand winding of repeating coil 267 and the called subscriber through the right hand windings of repeating coil 458. It is to be noted in this connection that inasmuch as the two offices in which the calling and called subscribers lines terminate have been assumed to be adjacent, only a portion of the right hand windings of the repeating coil 267 have been connected into the talking circuit and that therefore the ratio of transformation at the repeating coil 267 is less than would have resulted if the sequence switch 200 of the district selector had been arrested in position 13.

If the calling subscriber had dialed the number of a called line in a distant office, or had established connection to a toll trunk for communication with a district exchange, then the code letters which he would have dialed would have caused the energization of 130

both talking selection register relays 1017 and 1032, and as a consequence the sequence switch 200 at the district selector would have been arrested in position 13 rather than in position 12. With the sequence switch in position 13 the talking circuit extending from brush 263 of the district selector would then extend through the upper contacts of sequence switch cam 218, both sections of the 10 upper right hand winding of repeating coil 267, the lower left hand contact of sequence switch cam 220, condenser 270, the upper left hand contact of sequence switch cam 221, both sections of the lower right hand 15 winding of repeating coil 267, the upper contacts of sequence switch cam 219, and thence to brush 264 of the district selector.

If the calling subscriber had dialed the designation of a central office operator's position, then sequence switch 200 of the district selector would have been arrested in position 14 and following the response of the operator, polarized relay 268 would have so energized by current of reversed polarity 20 applied from the operator's cord circuit as to close its lower contacts. The circuit over which relay 268 is energized, upon such a connection, may be traced from brush 263, the upper contacts of sequence switch cam 218, the uppermost right hand winding of repeating coil 267, the upper contacts of sequence switch cam 220, the windings of polarized relay 268, the lower contact of sequence switch cam 221, the lowermost 25 right hand winding of coil 267, the upper contacts of sequence switch cam 219 and thence to the brush 264, this circuit being completed in the well known manner over the trunk circuit extending to the operator's 30 position. Relay 268, energizing in this circuit, closes a circuit for relay 228 which may be traced from grounded battery through the right hand winding of relay 228, the lower right hand contact of sequence switch cam 204, contacts of polarized relay 268 and 35 thence to ground through the upper left hand contact of sequence switch cam 214. Relay 228, upon energizing, closes a circuit for driving sequence switch 200 out of position 14 and into talking position 15, this circuit extending from grounded battery through the magnet winding of sequence switch 200, conductor 231, the upper left hand contact of sequence switch cam 206, 40 the inner right hand armature and front contact of relay 228 and thence to ground at the lower right hand contact and sequence switch cam 207.

Upon arriving in position 15, the circuit 45 previously traced through polarized relay 268 and the right hand windings of repeating coil 267 is opened and a direct metallic talking circuit is connected directly from trunk conductors 116 and 117 to the brushes 50 264 and 263 of the district selector switch,

the tip trunk conductor 117 being connected through the upper right hand contact of sequence switch cam 212 (14³ to 15), conductor 271 and thence to brush 263 and the ring conductor 116 of the trunk circuit being 55 connected through the upper left hand contact of sequence switch cam 213 (14³ to 15) over conductor 272 to brush 264 of the district selector switch. At this time supervisory relay 269 is disconnected from the 60 circuit previously traced through the calling subscribers station and slow releasing relay 227 is held energized over a locking circuit extending from grounded battery through its winding, conductor 273, the upper contacts of sequence switch cam 222, conductor 274, and thence to ground through the right hand armature and front contact of relay 227. Relay 228 is maintained locked 65 up after the energizing circuit previously traced through its right hand winding and the contacts of relay 268 is opened, by locking circuit extending from grounded battery through its left hand winding, its left hand armature and front contact, the upper contacts of sequence switch cam 215 and thence over test brush 257 of the district selector and the sleeve of the trunk extending to the operator's position.

Restoration of the connection between the calling line K and the called line L.

Upon the termination of the conversation both the calling and the called subscribers restore their respective receivers to their switch hooks. At this time relay 261 is energized, since this relay was energized as soon as sequence switch 200 reached position 12 provided the call was successful. The circuit for energizing relay 261 may be traced in the following manner: With sequence switch 200 in position 13 a circuit is closed for relay 276 extending from grounded battery through spring 277, closed by interrupter cam 278, through the winding of relay 276, the lower contacts of sequence switch spring 224, conductor 229, the lower contacts of relay 268 and thence to ground through the upper left hand contact of sequence spring 214. Relay 276, upon energizing, closes a locking circuit for itself independent of the interrupter spring 277, from grounded battery and through the left hand armature and back contact of relay 276. At its right hand armature and front contact relay 276 closes a circuit through spring 279 of the interrupter 278 after interrupter 278 has rotated sufficiently to open spring 277 and thence through the winding of relay 261 to grounded battery. Relay 261 100 which may be designated the charging relay, energizes in this circuit and closes a locking circuit for itself extending from grounded battery through its winding, the upper contacts of sequence switch spring 105 110 115 120 125 130

205 and thence to ground through the right hand armature and front contact of relay 261. At its left hand armature and front contact charging relay 261 prepares a circuit for charging the call as soon as the calling subscriber releases the connection.

Upon the restoration of the calling subscriber's receiver to the switch hook supervisory relay 269 de-energizes, opening the 10 circuit of relay 227. Relay 227, upon de-energizing, closes a circuit for driving sequence switch 200 out of position 12 and into position 17, this circuit extending from grounded battery through the winding of sequence switch magnet 200, the left hand contacts of sequence switch cam 223 and thence to ground at the back contacts of the right hand armature of relay 227. Upon 15 leaving position 16 the holding circuit extending over the sleeve conductor 118 and through the right hand winding of sleeve relay 226 is opened at sequence switch cam 203, but this relay is held energized in position 17 over a circuit extending from 20 grounded battery through its right hand winding, the left hand armature and front contact of charging relay 261, the lower left hand contact of sequence switch spring 203 and thence over sleeve conductor 118. In 25 position 17 battery is connected to the sleeve conductor 118, through the upper contacts of sequence switch spring 224, the outer left hand armature and front contact of sleeve relay 226, through the non-inductive left hand winding of relay 226, the left hand armature and front contact of charging relay 261, the lower left hand contact of sequence switch spring 203, thence over sleeve conductor 118, wiper 109 of trunk finding 30 switch 100, marginal register magnet 119, conductor 120, the intermediate lower armature and front contact of relay 102 and thence to ground through the upper winding of relay 102. The increased flow of 35 current through the winding of marginal register magnet 119 causes the operation of the register to register the call.

After a sufficient interval has elapsed to ensure the registering of the call, cam 281, 40 which is connected to the same shaft as cam 278, causes the closure of a circuit through the right hand winding of relay 228. This circuit may be traced from grounded battery through the right hand winding of relay 228, the upper right hand contact of sequence switch 204 and thence to ground 45 through the upper contacts of spring 282, closed upon the rotation of cam 281. Relay 228, upon energizing, closes a locking circuit for itself extending from grounded battery through its left hand winding its left hand armature and front contact and thence to ground through the upper left hand and lower right hand contacts of sequence switch cam 215. At its outer right

hand armature and front contact relay 228 closes a circuit for re-energizing relay 227 as soon as cam 281 has moved its spring 282 into contact with its lower contact. This circuit may be traced from grounded battery through the winding of relay 227, conductor 273, the left hand contacts of sequence switch cam 222, the outer right hand armature and front contact of relay 228, the contact of sequence switch cam 225 (17) and thence to ground through the lower contact of cam spring 282. Relay 227, upon energizing, closes a circuit for driving sequence switch 200 out of position 17 and into position 18. This circuit extends from grounded battery through the winding of sequence switch magnet 200, the upper left hand contact of sequence switch cam 206, the inner right hand armature and front contact of relay 228, the upper left hand contact of sequence switch cam 207 (17) and thence to ground at the right hand armature and front contact of relay 227. Sequence switch 200, upon leaving position 17, opens the locking circuit of relay 228 at sequence switch cam 215 and opens the circuit of relay 227 at sequence switch cam 222.

When sequence switch 200 leaves position 17 the holding circuit previously traced through the winding of relay 226 and the winding of cut off relay 102 of the subscriber's individual switch is opened and relays 227 and 102 de-energize. When sequence switch 200 reaches position 18, since at this time relay 227 is de-energized, a circuit is established for the down drive magnet of the district selector which may be traced from grounded battery through the winding of down drive magnet 283, the upper right hand and lower left hand contacts of sequence switch cam 203, conductor 275 and thence to ground at the back contact and right hand armature of relay 227. Down drive magnet 283, upon energizing, presses the depending portion of the switch shaft 246 against the constantly rotating down drive roller 284, thereby causing the movement of the switch shaft downwardly into normal position. As soon as the switch shaft reaches normal position a circuit is closed for driving sequence switch 200 out of position 18 and into position 1, this circuit extending from grounded battery through the winding of sequence switch magnet 200, the lower left hand contact of sequence switch cam 206, the normal segment 285 of the commutator 251, brush 256 and thence to ground at the lower left hand contact of sequence switch cam 214.

Upon the de-energization of cut off relay 102 a circuit is established through the stepping magnet 105 of the calling subscriber's individual switch 100 for restoring

- this switch into normal position. This circuit may be traced from grounded battery through the winding of stepping magnet 105 and its self interrupting armature contacts, conductor 106, the lowermost armature and back contact of relay 102, the right hand armature and back contact of relay 101, conductor 125, wiper 112 and thence to ground through the restoring segment 124. 5
- As soon as the switch 100 reaches normal position the wiper 112 will rest in normal position out of contact with segment 124 and the circuit of stepping magnet of relay 105 will be opened. The circuits of the subscriber's line and individual switch are now 10 in normal position.
- As soon as sequence switch 200 of the district selector leaves position 14₁, the circuit previously traced through the test brush 20 257, bank terminal 258, sleeve conductor 333 of the trunk extending to the office selector and thence through the lower right hand contact of sequence switch cam 305, the inner right hand armature and front 25 contact and right hand winding of relay 312, is opened at the right hand contacts of sequence switch cam 215, and relay 312 de-energizes. At the same time the circuit of relay 421 at the interoffice selector switch 30 35 450 is opened, this circuit extending from conductor 333 through the right hand contacts of sequence switch cam 305, brush 330 and bank terminal 344 of the office selector switch, the upper contact of sequence switch cam 407, conductor 427, the outer left hand armature and front contact of relay 421, conductor 431, the upper left hand contacts of sequence switch cam 409, the armature and back contact of relay 455 and thence 40 to grounded battery through the left hand winding of relay 421.
- Relay 312 of the office selector, upon de-energizing, closes a circuit for placing busy ground potential upon the bank terminal 45 50 55 60 65 70 75 80 85 90 95 100 105 110 115 120 125 130 and its multiples appearing in the banks of all district selector switches which have access to this trunk to prevent the seizure of the trunk until the office selector switch has completely restored to normal. This ground potential is applied over a circuit extending from sleeve conductor 333 through the lower right hand contact of sequence switch 305, the inner right hand armature and back contact of relay 312 and thence to ground 55 through the upper left hand contact of sequence switch 308 (5₁ to 18). At its left hand armature and back contact relay 312 closes a circuit for driving sequence switch 300 out of position 8 and into position 18. 60 This circuit extends from grounded battery through the magnet winding of sequence switch 300 conductor 324, the lower left hand contact of sequence switch cam 307, conductor 325, and thence to ground through 65 the left hand armature and back contact of relay 312. Upon reaching position 18, a circuit is closed for the down-drive magnet 338, which circuit extends from grounded battery through the winding of magnet 338 and thence to ground through the contacts 70 of sequence switch cam 306. The energization of magnet 338 presses the depending portion of switch shaft 317 against the constantly rotating down drive roller 339, thereby causing the movement of the switch shaft downwardly into normal position. As soon as the switch shaft reaches normal position, a circuit is closed for driving sequence switch 300 out of position 18 and into position 1, this circuit extending from grounded battery through the winding of sequence switch magnet 300, conductor 324, the lower right hand contact of sequence switch cam 307, normal segment 340 of commutator 321, brush 329, conductor 323 and thence to ground at the lower left hand contact of sequence switch cam 306. As soon as sequence switch 300 leaves position 18, the circuit of the down drive magnet 338 is opened to arrest the downward movement 90 of the switch shaft. The office selector and its associated circuits is now in normal contact.
- Upon the de-energization of relay 421 of the incoming selector switch 450, busy ground potential is connected to the sleeve conductor of the interoffice trunk over the upper contact of sequence switch cam 407, conductor 427, the outer left hand armature and back contact of relay 421 and thence to ground through the upper right hand and lower left hand contacts of sequence switch 411 for preventing the seizure of the interoffice trunk until after the incoming selector switch has been completely restored to normal. At its inner left hand armature and back contact relay 421 closes a circuit extending through the upper left hand contact of sequence switch cam 406 for driving sequence switch 400 out of position 16 and into 110 position 18. As soon as sequence switch 400 reaches position 18, a circuit is closed through the winding of the down drive magnet 461, extending from grounded battery through the winding of magnet 461 and thence to ground through the right hand contacts of sequence switch cam 410. Magnet 461, upon energizing, presses the depending portion of the switch shaft 432 against the constantly rotating down drive roller 462 thereby restoring the switch shaft to normal position. As soon as the switch shaft reaches its normal position a circuit is closed for driving sequence switch 400 out of position 18 and into normal position 1. This circuit may be traced from grounded battery through the winding of magnet 400, the upper right hand contact of sequence switch cam 406, normal segment 463 of the commutator 435, brush 441, conductor 437 130

and thence to ground through the lower contact of sequence switch cam 410. As soon as sequence switch 400 leaves position 18, the circuit of the down drive magnet 461 is opened to arrest the downward movement of the switch shaft and the busy ground potential is removed from the sleeve conductor of the interoffice trunk.

When sequence switch 400 of the incoming selector switch leaves position 16, the circuit previously traced through the contacts of sequence switch cam 412, over brush 442 and terminal 451 of the incoming selector, sleeve conductor 525, the left hand armature and front contact of relay 521, the armature and back contact of relay 524 and through the left hand winding of relay 521, over which circuit relay 521 has been held energized, is opened and relay 521, upon de-energizing, closes a circuit for energizing relay 518. This latter circuit may be traced from grounded battery through the left hand winding of relay 518, the upper contacts of sequence switch cam 509 and thence to ground at the armature and back contact of relay 521. Relay 518, upon energizing, closes a circuit for driving sequence switch 500 out of position 15 and into position 16. This circuit may be traced from grounded battery through the winding of magnet 500, the lower right hand contact of sequence switch cam 512, the left hand armature and front contact of relay 518 and thence to ground at the upper right hand contact of sequence switch cam 508.

When the sequence switch 500 leaves position 15, the energizing circuit of relay 518 is opened, but relay 518 maintains itself locked up over a circuit extending from grounded battery through the left hand contact of sequence switch cam 504, the right hand winding of relay 518, the lower contact of sequence switch cam 510, the right hand armature and front contact of relay 518, the lower left hand and upper right hand contacts of sequence switch cam 505, brush 553, bank terminal 557, over the subscriber's line loop, the bank terminal 559, brush 552, the lower right hand contacts of sequence switch cam 502 and thence to ground at the upper left hand contact of sequence switch cam 503. This locking circuit for relay 518 is maintained until the called subscriber restores his receiver to its switch hook, and the restoration of the final selector does not take place until the called subscriber has hung up.

In order to render the relay 518 more sensitive for releasing upon the restoration of the called subscriber's receiver to its switch hook, a shunt path is closed around the winding of relay 518 from grounded battery through the resistance element 560 and through the contact of sequence switch cam 516 which is closed in position 16.

When the called subscriber does hang up relay 518 becomes de-energized and, at its left hand armature and back contact closes a circuit for driving sequence switch 500 out of position 16 and into position 17. This circuit may be traced from grounded battery through the winding of sequence switch magnet 500, the upper right hand contact of sequence switch cam 512, the left hand armature and back contact of relay 518 and thence to ground at the upper right hand contact of sequence switch cam 508. Upon reaching position 17 sequence switch 500 is driven into position 18 over a circuit extending through its magnet winding, the lower right hand and upper left hand contacts of sequence switch cam 509 and to ground at the right hand armature and back contact relay 521. When sequence switch 500 reaches position 18 a circuit is closed for down-drive magnet 544 extending from grounded battery, through the winding of magnet 544, the lower right hand contact of sequence switch cam 511 (18), the upper right hand contact of sequence switch cam 507 (18) and thence to ground through the upper left hand contact of sequence switch cam 506. As soon as switch shaft 527 reaches normal position a circuit is closed for driving sequence switch 500 out of position 18 and into normal position 1, this circuit extending from grounded battery through the winding of magnet 500, the upper left hand contact of sequence switch cam 512, conductor 546, normal segment 547 of commutator 531, brush 538, conductor 533 and thence to ground at the upper left hand contact of sequence switch cam 506. The final selector and its associated circuits is now in normal position. During the restoration of the final selector to normal condition, the trunk extending to multiple terminals of the banks of all incoming selector switches having access thereto is held busy by ground potential connected to the sleeve conductor 525 of the trunk, over the left hand armature and back contact of relay 521 and the upper left hand contact of sequence switch cam 514. All apparatus which has been employed in the connection has now been restored to normal condition and may be used for establishing other calls.

If the calling subscriber had desired a connection with an office to which connection could be established without the employment of an office selector switch, then the three code letters dialed by the subscriber would have caused the energization of the skip office register relay 1012 in addition to the other register relays energized and locked up by the code impulses as previously described. With the skip office relay 1012 energized when the sequence switch 700 of the office sender reaches position 6 upon the termination of the group selection move-

ment of the district selector switch, the upper No. 0 counting relay 731 remains locked up and through position 10 for driving the sender sequence switch 700 directly into position 12 for controlling brush selection at the incoming selector switch. The locking circuit of relay 731 may be traced from grounded battery through the winding of the lower No. 0 counting relay 730, the winding of the upper No. 0 counting relay 731, the armature and front contact of relay 730, the upper left hand and lower right hand contacts of sequence switch cam 718, conductor 780 and thence to ground at the right hand armature and front contact of the skip office relay 1012. From this point the office sender functions in exactly the same manner as previously described.

What is claimed is:

1. In a telephone exchange system, incoming and outgoing lines, a link circuit to be used in interconnecting said lines, an auxiliary switch associated with said link circuit, a repeating coil associated with said link circuit, a primary winding and a secondary winding for said repeating coil, said secondary winding comprising a plurality of sectional windings, said sectional windings terminating in contacts controlled by said auxiliary switch, and means to position said auxiliary switch to connect in any desired number of said sectional windings to produce any desired ratio of turns between said primary winding and said secondary winding.

2. In a telephone exchange system, incoming and outgoing lines, a link circuit to be used interconnecting said lines, an automatic switch, movable contacts for said automatic switch in which one end of said link circuit terminates, an auxiliary switch associated with said link circuit serving to control certain operations of said automatic switch, a repeating coil associated with said link circuit, a primary winding and a secondary winding for said repeating coil, said secondary winding comprising a plurality of sectional windings, and means effective at a certain stage of operation to position said auxiliary switch to connect in any desired number of said sectional windings, to produce any desired ratio of turns between said primary and said secondary winding.

3. In a telephone exchange system, calling and called subscribers lines, a link circuit to be used in interconnecting said lines, an automatic switch, movable contacts for said automatic switch in which one end of said link circuit terminates, an auxiliary switch associated with said link circuit, a repeating coil associated with said link circuit, a primary winding and a secondary winding for said repeating coil, said secondary winding comprising a plurality of

sectional windings and means operated in accordance with the setting of said automatic switch for advancing said auxiliary switch to connect in any desired number of said sectional windings to produce any desired ratio of turns between said primary winding and said secondary winding.

4. In a telephone exchange system, calling and called subscribers lines, a link circuit to be used in interconnecting said lines, an automatic switch, movable contacts for said automatic switch in which one end of said link circuit terminates, an auxiliary switch associated with said link circuit, a repeating coil associated with said link circuit, a primary winding and a secondary winding for said repeating coil, said secondary winding comprising a plurality of sectional windings, a sending device to control the operation of said automatic switch, and means to variably position said auxiliary switch under the control of said sending device to connect in any desired number of said sectional windings to produce any desired ratio of turns between said primary and said secondary windings.

5. In a telephone exchange system, calling and called subscribers lines, a plurality of link circuits to be used in interconnecting said lines, an automatic switch individual to each of said link circuits, movable contacts for said automatic switch in which one end of the associated link circuit terminates, an auxiliary switch associated with each one of said link circuits, a repeating coil individual to each link circuit, a primary winding and a secondary winding for said repeating coil, said secondary winding comprising a plurality of sectional windings, a sending device common to said link circuits to control said automatic switches, means to associate said sending device with a desired link circuit, means to position the associated automatic switch under the control of said sending device, and means to variably position said auxiliary switch under the control of said sending device to connect in any desired number of said sectional windings to produce any desired ratio of turns between said primary windings and said secondary winding.

6. In a telephone exchange system, calling and called subscribers lines, a link circuit to be used in interconnecting said lines, an automatic switch, movable contacts for said automatic switch in which one end of said link circuit terminates, an auxiliary switch associated with said link circuit, a repeating coil associated with said link circuit, a primary winding and a secondary winding for said repeating coil, said secondary winding comprising a plurality of sectional windings, a sending device, means to operate said sending device in response to movement of said automatic switch, and means to operate said

sending device in response to movement of said auxiliary switch to control the variable positioning of said auxiliary switch to connect in any desired number of said sectional windings to produce any desired ratio of turns between said primary winding and said secondary winding.

7. In a telephone system an impulse sender, automatic switching means controlled thereby, trunk circuits for said switching means, a repeating coil, and means responsive to said sender to vary said coil for most

efficient transmission of talking current over the trunk circuit selected.

8. In a telephone system an impulse sender, automatic switching means controlled thereby, trunk circuits for said switching means, a repeating coil, and means responsive to said sender for varying the characteristics of said coil for most efficient transmission of talking current. 15

In witness whereof, I hereunto subscribe my name this 29 day of March A. D., 1921.

FREDERICK J. SCUDDER.
